ABSTRACT

Mounting systems for waste disposers such as food waste disposers, waste disposers employing such systems, and related methods are disclosed herein. In one example embodiment, a mounting system includes a tubular structure extending between first and second ends, and an enclosure structure configured to be able to support, at least indirectly, the waste disposer. Further, the mounting system includes an elastomeric member coupled to each of the tubular structure, the enclosure structure, and the waste disposer. Additionally, the mounting system includes one or more backup support features that is or are configured to enable the enclosure structure and the waste disposer to be supported relative to the tubular structure when the elastomeric member is unable unilaterally to provide a desired support level of the enclosure structure and the waste disposer relative to the tubular structure.

DISPOSER MOUNTING SYSTEM AND METHOD

FIELD

The present disclosure relates to waste disposers such as food waste disposers and methods of mounting such waste disposers in relation to other structures such as sinks and, more particularly, to waste disposer assemblies or mounting assemblies of or for such waste disposers, and methods of mounting such waste disposers in relation to other structures such as sinks, by way of such waste disposer assemblies or mounting assemblies.

BACKGROUND

Food waste disposers are used to comminute food scraps into particles small enough to pass through household drain plumbing. Referring to FIG. 1 (Prior Art), a conventional food waste disposer 10 is often mounted to a sink, such as a kitchen sink (not shown), and includes a food conveying section 12, a motor section 14, and a grinding section 16 disposed between the food conveying section and the motor section. The food conveying section 12 includes a housing 18 that forms an inlet for receiving food waste and water. The food conveying section 12 conveys the food waste to the grinding section 16, and the motor section 14 includes a motor imparting rotational movement to a motor shaft to operate the grinding section.

Conventional food waste disposers such as the food waste disposer 10 can be installed to a sink in a two-step procedure using a mounting assembly 100, an example of which is shown in FIG. 1 in an exploded manner relative to the food waste disposer. First, a sink flange assembly 102, which includes a sink (or strainer) flange 104, a sink gasket 106, a back-up flange 108, an upper mounting flange 110, bolts 112, and a retaining ring 114 are installed or mounted in relation to the sink (which again is not shown in FIG. 1). Second, a disposer assembly 30 including the food waste disposer 10 and also including a mounting (or sealing) gasket 116 and a lower mounting flange 118 are attached to the sink flange assembly 102. The combination of the disposer assembly 30 and the mounting assembly 100 can be considered to constitute an overall food waste disposer assembly 150.

More particularly with respect to the attachment of the disposer assembly 30 to the sink flange assembly 102, it should be understood that the lower mounting flange 118 is placed around the housing 18 that forms the inlet of the food conveying section 12. The mounting gasket 116 is then placed around that inlet as well, above the lower mounting flange 118, in a manner tending to secure the mounting gasket 116 to the inlet, by virtue of a lip at the inlet of the housing 18. Attachment of the disposer assembly 30 including the food waste disposer 10 to the sink flange assembly 102 and thereby to the sink is then particularly achieved by engaging mounting tabs 120 of the lower mounting flange 118 with ramps (or inclined mounting fasteners or edges or ridges) 122 of the upper mounting flange 110 and then rotating the lower mounting flange 118 relative to the upper mounting flange 110 until secure. When the lower mounting flange 118 and upper mounting flange 110 are secured together, the mounting gasket 116 is compressed therebetween, and provides a seal between the sink flange and inlet.

Although food waste disposers have long been successfully installed in relation to sinks in the manner described above (or in similar manners), mounting assemblies such as

the mounting assembly 100 are not ideal for all applications because the mounting assemblies establish fixed connections between the food waste disposers and the sinks to which those food waste disposers are attached and consequently can communicate significant amounts of potentially-annoying vibration to the sinks from the food waste disposers when those disposers are operating. In view of this concern, alternate mounting assemblies have been developed that can at least partly isolate, in terms of the communication of vibration, food waste disposers from the sinks in relation to which those disposers are installed. U.S. Pat. No. 5,924,635, which is beneficially assigned to Taisei Corporation and entitled "Vibration Isolation Installation Mechanism For a Disposer", which is hereby incorporated by reference herein, describes several such embodiments of vibration isolating installation mechanisms by which disposers can be coupled to sinks.

More particularly, in several such conventional mechanisms, a flexible cylinder is employed to link upper and lower cylindrical components of the mechanism/assemblies and additionally, radially outwardly from the flexible cylinder, support rods are provided that also link the upper and lower cylindrical components. Support of the lower cylindrical component relative to the upper cylindrical component is provided by way of the support rods, which are coupled to those cylindrical components by way of elastic bushings or springs in manner that reduces the amount of vibration that can be communicated between the lower and upper cylindrical components. Correspondingly, this reduces the amount of vibration that can be communicated between a disposer supported via the lower cylindrical component and a sink to which the upper cylindrical component is connected. Although support rods are employed in some of these conventional embodiments, in at least one other conventional embodiment the support rods are omitted and the lower and upper cylindrical components are coupled with one another solely by way of the flexible cylinder.

Notwithstanding the availability of such conventional vibration isolating installation mechanisms or mounting assemblies, such conventional mechanisms/assemblies can be disadvantageous in several respects. In particular, conventional mechanisms/assemblies that employ support rods externally of the flexible cylinder can be expensive to manufacture and complicated to install, due to the multiple parts associated with the support rods, elastic bushings or springs, and/or other associated componentry. The conventional mechanisms/assemblies involving the support rods also can entail undesirably-high axial space requirements in terms of the distances between the disposers and sinks, and may not be aesthetically pleasing. Alternatively, the conventional mechanism/assembly employing the flexible cylinder without the external support rods envisions that the flexible cylinder will provide all support of the lower cylindrical component and attached disposer relative to the upper cylindrical component (and sink to which it is attached). Should the flexible cylinder rupture over time (indeed, perhaps partly due to the vibrations experience by the cylinder due to ongoing disposer operation), the disposer could detach from the sink.

Accordingly, it would be desirable if an improved food waste disposer assembly (or other waste disposer assembly), and/or an improved mounting assembly of or for such a food waste disposer assembly (or other waste disposer assembly), and/or an improved method of installing or mounting such a waste disposer assembly or mounting assembly in relation to another structure such as a sink, could be developed that alleviated or addressed one or more of the above-discussed

concerns associated with conventional waste disposer assemblies, or alleviated or addressed one or more other concerns or disadvantages, or provided one or more advantages by comparison with conventional arrangements.

BRIEF SUMMARY

In at least some example embodiments, the present disclosure relates to a mounting system for mounting a waste disposer. The mounting system includes a tubular structure extending between first and second ends, and an enclosure structure having an additional end, where the enclosure structure is configured to be able to support, at least indirectly, the waste disposer. Further, the mounting system also includes an elastomeric member extending between the second end and the additional end, where the elastomeric member is coupled to each of the tubular structure and the enclosure structure, and serves to couple the tubular structure and the enclosure structure. Additionally, the mounting system includes a plurality of backup linkage members, where each of the plurality of backup linkage members is coupled at least indirectly to each of the tubular structure and the enclosure structure, and couples at least indirectly the tubular structure and the enclosure structure, and where each of the plurality of backup linkage members is integrally formed or molded with at least one of the tubular structure and the enclosure structure.

Additionally, in at least some example embodiments, the present disclosure relates to a waste disposer assembly that includes a waste disposer and a mounting assembly. The mounting assembly includes a first structure having a first end and a second end, and configured to be coupled at or proximate the first end to a support structure. The mounting assembly also includes a second structure having an additional end, where the waste disposer is at least indirectly attached to and supported by the second structure, and an anti-vibration linking structure extending between and coupling the second end and the additional end. Further, the mounting assembly includes a plurality of supplemental linking structures coupling the first structure and the second structure, where each of the supplemental linking structures is integrally formed or molded with respect to each of the first structure and the second structure. Additionally, the anti-vibration linking structure is overmolded around, so as to substantially encapsulate, each of the supplemental linking structures.

Further, in at least some example embodiments, the present disclosure relates to a method of assembling a mounting system for use in coupling a food waste disposer to a sink. The method includes forming a mounting subassembly including a tubular structure, an enclosure structure, and a plurality of first linking structures, where all of the tubular structure, the enclosure structure, and first linking structures are formed integrally. Also, the method includes applying an elastomeric material to the mounting subassembly, so as to provide an elastomeric formation extending between the tubular structure and the enclosure structure, and so as to couple the enclosure structure with the tubular structure. Further, the elastomeric formation serves as a primary linking structure by which the enclosure structure is supported in relation to the tubular structure, and the first linking structures are backup linking structures, and also the elastomeric formation is configured to prevent or reduce a communication of vibrations between the tubular structure and the enclosure structure.

Additionally, in at least some example embodiments, the present disclosure relates to a mounting system for mounting

a waste disposer. The mounting system includes a tubular structure extending between first and second ends, and an enclosure structure that is configured to be able to support, at least indirectly, the waste disposer. Also, the mounting system includes an elastomeric member coupled to each of the tubular structure, the enclosure structure, and the waste disposer, and one or more backup support features. The one or more backup support features is or are configured to enable the enclosure structure and the waste disposer to be supported relative to the tubular structure when the elastomeric member is unable unilaterally to provide a desired support level of the enclosure structure and the waste disposer relative to the tubular structure.

Further, in at least some example embodiments, the present disclosure relates to a waste disposer assembly. The waste disposer assembly includes a waste disposer and a mounting assembly. The mounting assembly includes a first structure having a first end and a second end, and configured to be coupled at or proximate the first end to a support structure, and also includes a second structure having an additional end, where the waste disposer is at least indirectly attached to and supported by the second structure. Also, the mounting assembly includes an anti-vibration linking structure coupled to each of the second end of the first structure, the additional end of the second structure, and the waste disposer, and at least one backup support feature. The at least one backup support feature is configured to support, at least in part, the second structure and the waste disposer relative to the first structure, in an operational circumstance in which the anti-vibration linking structure is unable to provide a desired support level of the second structure and the waste disposer relative to the first structure.

Additionally, in at least some example embodiments, the present disclosure relates to a method of operating a waste disposer assembly. The method includes providing a waste disposer and a mounting assembly. The mounting assembly includes a first structure having a first end and a second end and configured to be coupled at or proximate the first end to a support structure, and a second structure having an additional end, wherein the waste disposer is at least indirectly attached to and supported by the second structure. The mounting assembly also includes an anti-vibration linking structure coupled to each of the second end and the additional end, and at least one backup support feature. Further, the method also includes first supporting the second structure and the waste disposer relative to the first structure by the anti-vibration linking structure when the waste disposer assembly is in a normal operational state. Additionally, the method also includes second supporting the second structure and the waste disposer relative to the first structure, at least in part, by the at least one backup support feature, when the waste disposer assembly is in an alternative backup support state in which the anti-vibration linking structure is unable to provide a desired support level of the second structure and the waste disposer relative to the first structure. The at least one backup support feature includes a first portion of the second structure at or proximate the additional end and a rim portion of the first structure at or proximate the second end, and the second supporting includes supporting the first portion of the second structure upon the rim portion of the first structure.

BRIEF DESCRIPTION OF THE DRAWINGS

Embodiments of food waste disposer assemblies (or other waste disposer assemblies), mounting assemblies of or for such waste disposer assemblies, and related methods are

disclosed with reference to the accompanying drawings and are for illustrative purposes only. The waste disposer/mounting assembly apparatuses and methods encompassed herein are not limited in their applications to the details of construction, arrangements of components, or other aspects or features illustrated in the drawings, but rather such apparatuses and methods encompassed herein include other embodiments or are capable of being practiced or carried out in other various ways. Like reference numerals are used to indicate like components. In the drawings:

FIG. 1 is an exploded view of a Prior Art food waste disposer assembly including both a mounting assembly and a disposer assembly including a food waste disposer, as can be installed in relation to another structure such as a sink;

FIG. 2 is a partly cross-sectional, partly front elevation view of an example improved food waste disposer assembly having an improved mounting assembly mounted in relation to a sink, in accordance with an example embodiment encompassed herein;

FIG. 3 is a front elevation view of portions of a first embodiment of the food waste disposer assembly represented by FIG. 2 including portions of a first embodiment of the improved mounting assembly, which includes a plurality of springs integrally formed with an anti-vibration (AV) tube and enclosure, and in which the springs are overmolded with an elastomeric material that forms an additional annular structure;

FIG. 4 is an additional front elevation view of the cutaway portions (or portions thereof) of the first embodiment of the food waste disposer assembly (including portions of the first embodiment of the improved mounting assembly) of FIG. 3, where the integrally formed springs are revealed by way of a phantom view;

FIG. 5 is a cross-sectional view of the cutaway portions (or portions thereof) shown in FIG. 4, taken along a line 5-5 in FIG. 4;

FIG. 6 is a front elevation view of further cutaway portions of the integrally-formed springs, AV tube and enclosure of the first embodiment of the food waste disposer assembly of FIG. 3, prior to an overmolding step (and thus with the additional annular structure of FIG. 3, FIG. 4, and FIG. 5 not being present);

FIG. 7 is a cross-section of the further cutaway portions of FIG. 4 taken along line 7-7 of FIG. 6, at a time after an overmolding step has occurred such that additional annular structure of FIG. 3, FIG. 4, and FIG. 5 is also shown, in cross-section, to be present in relation to those cutaway portions;

FIG. 8 is a flow chart illustrating example steps of assembly of the first embodiment of the improved mounting assembly of the food waste disposer assembly shown in FIG. 3, FIG. 4, FIG. 5, FIG. 6, and FIG. 7;

FIG. 9 is a front elevation view of portions of a second embodiment of the food waste disposer assembly represented by FIG. 2 including portions of a second improved mounting assembly, in which the improved mounting assembly includes a plurality of living hinges integrally formed with an anti-vibration (AV) tube and enclosure, and in which the living hinges are overmolded with an elastomeric material that forms an additional annular structure;

FIG. 10 is an additional front elevation view of additional cutaway portions (or portions thereof) of the second embodiment of the improved mounting assembly of the food waste disposer assembly of FIG. 9, where the integrally formed living hinges are revealed;

FIG. 11 is a detail view of the additional cutaway portions of FIG. 10 that more clearly reveals features of one of the living hinges;

FIG. 12 is a front elevation view of cutaway portions of a third embodiment of the food waste disposer assembly represented by FIG. 2 including portions of a third improved mounting assembly, in which the improved mounting assembly includes a plurality of top-down external suspenders, an anti-vibration (AV) tube, and enclosure, and also including elastomeric material that forms a tension mount;

FIG. 13 is a cross-sectional view of an additional example improved food waste disposer assembly having an improved mounting assembly encompassed herein, where the cross-section is taken along a vertical central axis of the improved food waste disposer assembly;

FIG. 14 is a detail view of a cutaway portion of the improved food waste disposer assembly of FIG. 13;

FIG. 15 and FIG. 16 are front elevation views of cutaway portions of further example embodiments of the food waste disposer assembly represented by FIG. 2, which respectively have respective additional improved mounting assemblies; and

FIG. 17 is a front elevation view of an additional cutaway portion of an additional improved mounting assembly that can be implemented, in an alternate embodiment, instead of either of the additional improved mounting assemblies of FIG. 15 and FIG. 16.

DETAILED DESCRIPTION

Referring to FIG. 2, an improved food waste disposer assembly 200 in accordance with an example embodiment encompassed herein is installed or mounted in relation to a sink 202. Although FIG. 2 shows a side elevation view of the food waste disposer assembly 200, FIG. 2 provides a cutaway cross-sectional view of the sink 202, so as to better illustrate how the food waste disposer assembly is installed relative to the sink. The food waste disposer assembly 200 particularly includes a disposer assembly 204 that includes a food waste disposer 206 and an improved mounting assembly 208 that allows for the disposer assembly 204 to be attached to the sink 202, so as to be positioned beneath the sink.

In the present embodiment, the improved mounting assembly 208 particularly includes an anti-vibration (AV) tube 210, an enclosure 212, and an overmolded section 214 positioned between and coupling the AV tube with the enclosure. Also, the improved mounting assembly 208 includes coupling components 215, which in the present embodiment include the mounting (or sealing) gasket 116 and lower mounting flange 118 described above with reference to FIG. 1 (or components substantially similar to those components). As described further below, the AV tube 210 (which can also be referred to as a top enclosure piece or neck) can be mounted or coupled by way of the coupling components 215 to a sink flange assembly 216 of the sink 202. In the present embodiment, the sink flange assembly 216 is identical or substantially identical to the sink flange assembly 102 described above with reference to FIG. 1, and particularly includes the sink flange (or strainer flange) 104, which defines a bottom drain orifice 218 of the sink 202, as well as the upper mounting flange 110.

The enclosure 212, which can also be referred to as a bottom enclosure piece (or grind enclosure or container body), is positioned beneath the AV tube 210 and coupled therewith by way of the overmolded section 214. The enclosure 212 particularly serves to support the disposer

assembly 204 including the food waste disposer 206, which is positioned beneath and coupled to that enclosure. Although for purposes of the present disclosure, the sink flange assembly 216 is considered to be a part of the sink 202, alternatively the sink flange assembly (or portions thereof, such as the upper mounting flange 110) can be considered part of the improved mounting assembly 208 (in some such cases, the improved mounting assembly can also be considered an improved sink flange assembly). Likewise, although for purposes of the present disclosure the coupling components 215 are considered to be part of the improved mounting assembly 208, alternatively the coupling components (or portions thereof, such as the lower mounting flange 118) can be considered part of the sink flange assembly.

Although the food waste disposer 206 of FIG. 2 can be the same or substantially similar to the food waste disposer 10 of FIG. 1, in alternate embodiments other types of food waste disposers can be employed. Indeed, the present disclosure is intended to encompass a wide variety of embodiments including embodiments having other types of waste disposers (including waste disposers that are suited for disposing of other materials rather than food) as well as waste disposers that are to be mounted in relation to other types of structures instead of sinks. Further, although it is envisioned in the present embodiment that the enclosure 212 is a structure that is distinct from (even though coupled to) the food waste disposer 206, it should be appreciated that in other embodiments the enclosure 212 can form a housing (e.g., a cylindrical housing) within which the food waste disposer 206 is situated and supported.

Turning to FIG. 3, a perspective view shows the improved mounting assembly 208 of FIG. 2 apart from the sink 202 and the food waste disposer 206, so as to highlight several features of that mounting assembly in particular. In this view, the overmolded section 214 is again visible, and is particularly shown to include an annular elastomeric formation 300 extending between a bottom circumferential lip 302 of the AV tube 210 and a top circumferential lip 304 of the enclosure 212. The annular elastomeric formation 300 can be made, for example, from a thermoplastic elastomer (TPE) or other elastomeric material. By virtue of employing such a material, the annular elastomeric formation 300 is configured to serve an anti-vibration or vibration-attenuation purpose—particularly in terms of eliminating or reducing the amount of vibration that can be communicated from the enclosure 212 to the AV tube 210, and thus in terms of eliminating or reducing the amount of vibration that can be communicated from the food waste disposer 206 of the disposer assembly 204 to the sink 202 when the disposer assembly 204 is coupled to the enclosure 212 and the AV tube 210 is coupled to the sink.

Additionally as shown in FIG. 3, the AV tube 210 also includes an additional top circumferential lip (or rim) 306, and extends upward from the bottom circumferential lip 302 to the top circumferential lip 306. The top circumferential lip 306 particularly extends around and defines a top orifice 308 of the AV tube 210. It should be appreciated that, when the improved food waste disposer assembly 208 is coupled to the sink 202, the top orifice 308 is aligned with the bottom drain orifice 218 of the sink flange assembly 216 (as particularly established by a bottom circumferential edge of the sink flange 104). Given such an arrangement, food waste entering the bottom drain orifice 218 of the sink 202 (as shown in FIG. 2) will proceed into the food waste disposer assembly 200 via the top orifice 308 of the AV tube 210 of the improved mounting assembly 208.

Further, the top circumferential lip 306 enables the coupling components 215 to couple the AV tube 210 to the sink flange assembly 216. More particularly, during installation of the improved food waste disposer assembly 200 in relation to the sink 202, the lower mounting flange 118 of the coupling components 215 is positioned so as to extend around the AV tube 210, between the top circumferential lip 306 and bottom circumferential lip 302. Additionally, the mounting gasket 116 is positioned around the top circumferential lip 306. More particularly, the mounting gasket 116 has an internal groove (e.g., a groove along its inner circumference) that captures the top circumferential lip 306. Before installation is complete, the lower mounting flange 118 can rest upon the top surface of the bottom circumferential lip 302. However, to achieve installation, the lower mounting flange 118 of the coupling components 215 is coupled to the upper mounting flange 110 of the sink flange assembly 216, with both the top circumferential lip 306 of the AV tube 210 as well as the mounting gasket 116 being positioned between those two flanges.

Given such an arrangement, a portion (e.g., an annular portion) of the mounting gasket 116 extends below the top circumferential lip 306, and the lower mounting flange 118 particularly contacts this portion of the mounting gasket (e.g., abuts the lower surface or underside of the mounting gasket, which in turn is in contact with the top circumferential lip along its internal groove), such that the top circumferential lip 306 is supported upon the lower mounting flange 118 indirectly by way of the mounting gasket 116 therebetween (that is, the lower mounting flange 118 does not directly contact the top circumferential lip 306 but still nevertheless that lip is supported indirectly by that flange via the mounting gasket). Additionally, given this arrangement, the lower mounting flange 118 compresses the mounting gasket 116 around and in relation to the top circumferential lip 306, so as to create a seal and prevent leakage. Accordingly, the entire AV tube 210—and all of the remaining portions of the improved mounting assembly 208 and improved food waste disposer assembly 200 supported by the AV tube—are supported in relation to the sink 202.

Referring additionally to FIG. 4, FIG. 5, FIG. 6, and FIG. 7, further views are provided of portions of the improved mounting assembly 208 that are intended to reveal additional features of the overmolded section 214. FIG. 4 particularly provides a cutaway perspective view of portions of the improved mounting assembly 208, with bottom portions of the improved mounting assembly particularly being cutaway and the remaining illustrated portions being enlarged. The orientation of the improved mounting assembly 208, in term of the perspective view shown, is the same as that of FIG. 3. FIG. 5 provides an additional cross-sectional view of cutaway portions of the improved mounting assembly 208, which can be understood for example as corresponding to a section taken along line 5-5 of FIG. 4, except insofar as additional portions of the AV tube 210 and enclosure 212 are additionally cutaway by comparison with what is shown in FIG. 4.

More particularly with respect to FIG. 4, it should be recognized that, in addition to showing the annular elastomeric formation 300 extending between the AV tube 210 and the enclosure 212, FIG. 4 shows that the overmolded section 214 further includes multiple spring formations (or simply springs) 400. As illustrated, the springs 400 extend between the AV tube 210 and the enclosure 212, and in at least some embodiments can be accordion-shaped structures. Further, in the present embodiment, all of the springs 400 are integrally formed with the AV tube 210 and the enclosure

212. That is, the AV tube 210, enclosure 212, and the springs 400 all are molded from a single piece of plastic material, which can (for example) be a polymer plastic material, and which is distinct from the material forming the annular elastomeric formation 300. The springs 400, AV tube 210, and enclosure 212 can be considered to form a single integral mounting subassembly 600 (see FIG. 6), and also can generally be considered a substrate of the improved mounting assembly 208.

Also, in the present embodiment, each of the springs 400 includes a respective first ramp portion 404 and a respective second ramp portion 406 that are integrally connected at a respective junction 408 (which can be implemented without sharp points or be rounded to some extent, to facilitate manufacture and/or extend operational life). More particularly, the respective first ramp portion 404 of each of the respective springs 400 extends from a respective circumferential location 410 along the bottom circumferential lip 302 of the AV tube 210 toward the enclosure 212, to the respective junction 408, and the respective second ramp portion 406 of each respective spring extends from the respective junction to a respective circumferential location 412 along the top circumferential lip 304 of the enclosure 212. Additionally as shown, the respective first ramp portion 404 of each of the springs 400 is generally inclined in a first circumferential direction (e.g., clockwise, as one proceeds away from the AV tube 210 toward the enclosure 212) and the respective second ramp portion 406 of each of the springs is generally inclined in a second circumferential direction (e.g., counterclockwise, as one proceeds away from the AV tube toward the enclosure).

Additionally, it should be recognized from FIG. 4 that the springs 400 (which are intended to be shown relative to the annular elastomeric formation 300 in a ghosted or phantom manner) are surrounded by and encapsulated (or substantially encapsulated) within the annular elastomeric formation 300. That is, the annular elastomeric formation 300 is formed in relation to the AV tube 210, the enclosure 212, and the springs 400 so as to extend between and fill in the gaps between the AV tube 210, the enclosure 212, and the springs 400. In particular, none of the springs 400 is positioned radially outwardly, relative to the center line or axis 402 of the improved mounting assembly 208, so as to extend radially outwardly beyond the annular elastomeric formation 300. Rather, the annular elastomeric formation 300 by itself forms the outer circumference of the overmolded section 214, including the springs 400 thereof.

To achieve such an arrangement, the annular elastomeric formation 300 is formed by injecting and overmolding the TPE or other elastomeric material (or other material) used to form that annular elastomeric formation in relation to the integrally-formed assembly of the AV tube 210, enclosure 212, and springs 400. In particular, as illustrated by FIG. 5, which does not show any of the springs 400, the annular elastomeric formation 300 (upon being fully formed) in the present embodiment extends radially inwardly from an outer circumferential edge 500 that is slightly radially-outward of an outer circumference 502 of the bottom circumferential lip 302 of the AV tube 210 (but that is still positioned radially-inwardly relative to the outer circumference of the top circumferential lip 304) to an inner circumferential edge 504 that is slightly radially-inward of an inner circumference 506 of that bottom circumferential lip 302. In this manner, the annular elastomeric formation 300 extends beyond or overhangs the bottom circumferential lip 302, both along the outer circumference 502 and inner circumference 506, and thus extends radially outwardly and radially inwardly to

farther extents than do any of the springs 400. It can be further noted that in the present embodiment the outer circumferential edge 500 tapers slightly radially-outward (e.g., takes a frustoconical shape) as one proceeds from the bottom circumferential lip 302 to the top circumferential lip 304, although in other embodiments the edge can be non-tapering, tapered in a different manner, or have some other curvature.

Turning to FIG. 6 and FIG. 7, additional views are provided of portions of the improved mounting assembly 208 that are intended to highlight certain features of the improved mounting assembly 208 and also intended to inform a process of assembling the improved mounting assembly discussed in relation to FIG. 8 below. In particular, FIG. 6 provides an additional cutaway view of portions of the improved mounting assembly 208, in which all four of the springs 400 (along with portions of the AV tube 210 and the enclosure 212) are visible, but in which the annular elastomeric formation 300 is absent. The view provided in FIG. 6 can be considered a side (e.g., right side) elevation view of portions of the mounting subassembly 600, including the combination of the springs 400, the AV tube 210, and the enclosure 212, where portions of the AV tube 210, the enclosure 212, and one of the springs are cutaway.

Additionally, referring to FIG. 7, a further cross-sectional view of cutaway portions of the improved mounting assembly 208 is provided. The cross-sectional view of FIG. 7 can be understood for example as corresponding to a section taken along line 7-7 of FIG. 6, except insofar as portions of the annular elastomeric formation 300 are now present and insofar as additional portions of the AV tube 210 and enclosure 212 are cutaway by comparison with what is shown in FIG. 6. Among other things, it can be appreciated from FIG. 7 that the annular elastomeric formation 300 extends between the respective first and second ramp portions 404, 406 of each respective spring at locations such as a location 700 at which those ramp portions are apart from one another (e.g., other than at the respective junction 408 linking those ramp portions).

Notwithstanding the configuration of the springs 400 described above, it should be appreciated that, in other embodiments, the springs can take other forms. For example, the inclination of the ramp portions can vary from that described above (e.g., different ones of the springs can have ramp portions that are inclined in different manners), and/or one or more of the springs can include more than two ramp portions or include other (e.g., non-ramped, or vertical) portions. Also, even though each of the ramp portions 404, 406 in the present example embodiment are generally straight structures, in other embodiments one or more of the ramp portions can be curved. Additionally, although in the present embodiment it is envisioned that there are four of the springs 400, which are circumferentially spaced equidistantly from one another around a center line of the 402 of the improved mounting assembly (and of the AV tube 210 and enclosure 212 thereof), in alternate embodiments the number or relative spacing of the springs 400 can vary from that shown. For example, in some alternate embodiments, there can be two, three, six, or eight springs, and/or certain neighboring ones of the springs can be positioned more closely to one another than other neighboring ones of the springs. Indeed, in general, the geometries and number of springs can be set or iterated to optimize the anti-vibration performance of the spring-overmold mount.

In the present example embodiment, the springs 400 fulfill multiple roles. First, although it is intended that the annular elastomeric formation 300 serve as the primary

support structure linking the AV tube 210 and the enclosure 212, the springs 400 can serve a backup support structure. That is, although it is intended that the annular elastomeric formation will serve as the primary weight bearing structure allowing for any weight coupled to the enclosure (e.g., the disposer assembly 204 with the food waste disposer 206) to be borne by the AV tube (and any structure supporting the improved food waste disposer assembly 200 such as the sink 202), the springs 400 can also provide such support. This can be beneficial, for example, if over time the annular elastomeric formation 300 experiences creeping or becomes distended, or if for some reason the annular elastomeric formation itself ceases to fully or substantially couple the AV tube 210 with the enclosure 212 (for example, if adhesive used to link the annular elastomeric formation 300 with the AV tube or enclosure weakens). In short, the springs 400 provide a redundant coupling mechanism by which the AV tube 210 and enclosure 212 are linked, so as to supplement the coupling provided by the annular elastomeric formation 300.

Second, in the present embodiment, the springs 400 also provide a mechanism by which a pre-load (in tension or compression) can be implemented as an aspect of the improved mounting assembly 208. As described further below in regard to FIG. 8, such a pre-load can be applied at the time of the overmolding process. This can permit the TPE or other elastomeric material (or other material serving as an overmold material) employed to form the annular elastomeric formation 300 to be influenced with regard to its loading during post-installation service. Such manner of implementation can serve to offset weight associated with a unit or structure that is borne by the enclosure 212 (e.g., the food waste disposer 206), and/or has the potential to achieve an optimal state for performance and structural integrity. In some circumstances, it is envisioned that the springs 400 and annular elastomeric formation 300 can promote a spring/dashpot dampening effect.

Referring now to FIG. 8, a flow chart 800 is provided to illustrate an example process or method of manufacturing or assembly of the improved mounting assembly 208. As will be described in further detail below, the improved mounting assembly 208 can be formed in a variety of manners that may or may not include pre-loading, so that the improved mounting assembly in its completed form may or may not provide an offset relative to loading that may occur subsequently. As shown in the flow chart 800, upon the assembly process commencing at a start step 802, then at a first step 804 the mounting subassembly 600 including the AV tube 210, the enclosure 212, and the springs 400 extending therebetween is integrally formed (e.g., molded out of polymer plastic). The formation of the mounting subassembly 600 (or substrate) can in some embodiments be performed through the use of multiple slides in the molding tool. For example, with reference to FIG. 6, two slides could be employed to form a portion of the mounting subassembly 600 including the spring 400 through which the line 7-7 extends, where the two slides upon forming that spring would be removed apart from one another in opposite directions perpendicular to the line 7-7 as represented by first and second arrows 414 and 416.

Next, at a second step 806, it is determined whether, and to what extent, a pre-load (in tension or compression) should be applied to the mounting subassembly 600, and particularly to the springs 400 thereof. This determination for example can be made during manufacturing, and in some cases can be made automatically (e.g., by a computer). In at least some circumstances or embodiments, this determina-

tion takes into account the expected loading that will be experienced by the improved mounting assembly 208 (e.g., due to the weight of the food waste disposer 206).

Subsequently, at a third step 808, if it is determined at the second step 806 that a pre-load should be applied, then that pre-load is applied to the mounting subassembly 600 (and particularly to the springs 400 thereof) or, alternatively, if it is determined at the second step 806 that no pre-load should be applied, then the mounting subassembly 600 is left in a neutral (e.g., unloaded) state. A preload involving a preset tension can be applied at the step 808, for example, by applying a tension force between the AV tube 210 and the enclosure 212 as represented by first arrows 602 in FIG. 6, and a preload involving a preset compression can be applied at the step 808, for example, by applying a compression upon the AV tube and the enclosure relative to each other as represented by second arrows 604 in FIG. 6.

Next, at a fourth step 810, an elastomer is applied to the mounting subassembly 600 to form the combination of structures that are comprised by the improved mounting assembly 208. As already described above, this application involves overmolding the elastomer relative to the AV tube 210, the enclosure 212, and the springs 400, especially in a manner so that the elastomer fills in the gaps among these components and couples the AV tube 210 with the enclosure 212, as well as surrounds or encapsulates (or substantially encapsulates) the springs. By virtue of this step, the elastomer forms the annular elastomeric formation 300 and, in combination with the springs 400, forms the overmolded section 214. The elastomer applied at the fourth step 810 can be, as mentioned above, TPE or another elastomeric material (or other material). In at least some embodiments, the elastomer can be applied by way of injection (e.g., during a “neck fill”).

Upon the completion of the fourth step 810, the process of FIG. 8 further advances to a fifth step 812, after which the process ends at an end step 814. At the fifth step 812, a post-overmolding state is achieved by the improved mounting assembly 208 due to the solidifying of the elastomer applied at the step 810. The post-overmolding state that is achieved at the fifth step 812 particularly may be influenced by any pre-loading that was applied at the third step 808. For example, if a preload involving a preset tension was applied at the step 808 (as represented by the first arrows 602), then the post-overmolding state that will be achieved at the fifth step 812 will be a state in which the annular elastomeric formation 300 experiences compression as represented by third arrows 702 shown in FIG. 7. Such compression would occur due to the springs 400 of the improved mounting assembly 208 tending to return to their unstressed (without the preset tension) state. Also for example, if a preload involving a preset compression was applied at the step 808 (as represented by the second arrows 604), then the post-overmolding state that will be achieved at the fifth step 812 will be a state in which the annular elastomeric formation 300 experiences tension as represented by fourth arrows 704 shown in FIG. 7. Such tension would occur due to the springs 400 of the improved mounting assembly 208 tending to return to their unstressed (without the preset compression) state. Additionally as will be appreciated, if no preload involving a preset compression or tension is applied at the third step 808, then the annular elastomeric formation 300 would not tend to experience tension or compression post-overmolding (at least until such time as the improved mounting assembly 208 experiences a load such as due to the attachment of the food waste disposer 206).

Although the process represented by the flow chart 800 particularly is intended to relate to the manufacturing or assembling of the improved mounting assembly 208, this process can be understood as also encompassing or extending to encompass additionally the loading of the improved mounting assembly, as represented by a further step 816. Such loading can occur, for example, when a food waste disposer such as the food waste disposer 206 is attached to the enclosure 212 of the improved mounting assembly 208. It should be appreciated that the further step 816 is shown in dashed lines in FIG. 8 because that step would typically occur after completion of the process of manufacturing or assembling of the improved mounting assembly 208 (rather than being considered part of that process), and can be considered a step of a larger process of manufacturing or assembling the food waste disposer assembly 200 including both the disposer assembly 204 (that includes the food waste disposer 206) and the improved mounting assembly 208. As further represented by an arrow 706 shown in FIG. 7, the application of a load to the improved mounting assembly 208 will typically cause a downward tension force to be applied to the improved mounting assembly.

Referring still to FIG. 8, it should be recognized that the process 800 can be performed in multiple different manners. In particular, the process can be performed in different manners that involve different levels of pre-loading (or absence thereof) with respect to the mounting subassembly 600 and particularly the springs 400 thereof. Further, depending upon the level of pre-loading of the mounting subassembly 600/springs 400 that is applied (or not applied), different post-overmolding states of the TPE or other elastomeric material (or other material) of the overmolded section 214, and of the improved mounting assembly 208 as a whole, as well as of the entire food waste disposer assembly 200 when the disposer assembly 204 is attached to the improved mounting assembly, can be achieved.

More particularly, FIG. 8 shows a first side-box 818 that is provided to illustrate five example pre-load scenarios, in terms of the level of pre-loading that is applied or not applied with respect to the mounting subassembly 600/springs 400. A dashed line 822 is shown to link the first side-box 818 with the third step 808, as it is during the third step that pre-loading is applied to the mounting subassembly 600/springs. The first side-box 818 particularly illustrates the following pre-load scenarios: (A) a first scenario in which only a small preset tension (e.g., tension level A) is applied to mounting subassembly 600/springs 400; (B) a second scenario in which a medium preset tension (e.g., tension level B) is applied to the mounting subassembly/springs; (C) a third scenario in which a large preset tension (e.g., tension level C) is applied to the mounting subassembly/springs; (D) a fourth scenario in which no pre-load (no preset tension or preset compression) is applied to the mounting subassembly/springs; and (E) a fifth scenario in which a preset compression is applied to the mounting subassembly/springs.

It should be appreciated that any arbitrary level or magnitude of tension or compression can be applied at the third step 808. However, the five (5) pre-load scenarios that are shown in the first side-box 818 have been chosen because the scenarios can result in qualitatively different outcomes, in terms of post-overmolding states of the improved mounting assembly 208 and the overall food waste disposer assembly 200. Given these different scenarios in terms of the application (or absence of application) of pre-loading to the mounting subassembly 600/springs 400, the TPE or other elastomeric material (or other elastomer or material) of the

overmolded section 214 can experience different levels of tension or compression (or absence thereof) after the overmolding has occurred at the step 810. Additionally, although the TPE or other elastomeric material (or other elastomer or material) can experience such post-overmolding tension or compression subsequent to overmolding even when no weight is applied to the improved mounting assembly 208, such tension or compression that is experienced by the TPE or other elastomeric material (or other elastomer) and by the improved mounting assembly overall can additionally change when a weight such as that due to the food waste disposer 206 is attached to improved mounting assembly 208.

More particularly in this regard, the post-overmold states of the improved mounting assembly shown in the second side-box 820 include five possible pairs of states (A, B, C, D, and E) that respectively correspond to the respective five pre-load scenarios shown in the first side-box 818 (A, B, C, D, and E discussed above), with the correspondence being in shown in FIG. 8 by connecting arrows 826. Each of the five pairs of states illustrated by the second side-box 820 encompasses two states (or sub-states), namely, a first “unweighted” post-overmolded state of the improved mounting assembly 208 that is reached at the fifth step 812, prior to the improved mounting assembly being loaded by any additional weight (such as that of the food waste disposer 206), and also a second “weighted” state of the improved mounting assembly that is reached when a load is applied to the improved mounting assembly (e.g., due to the attachment of the food waste disposer 206) at the step 816. That the states represented by the second side-box 820 are achieved at the step 812 or the step 816 is indicated by a dashed link 824 connecting the second side-box 820 with each of the fourth step 812 and the step 816 as well.

It should be appreciated that there exists correlations between the pre-load scenarios and the post-overmolding states as represented in the side-boxes 818 and 820. In general, if tension is applied to the mounting subassembly 600/springs 400 prior to overmolding, then the springs post-overmolding will tend to return to their natural, unstressed position, and consequently the TPE or other elastomeric material (or other material) applied during overmolding will tend to be compressed. Inversely, if the mounting subassembly 600/springs 400 are compressed prior to overmolding, then the springs post-overmolding will tend to return to their natural, unstressed position, and consequently the TPE or other elastomeric material (or other material) applied during overmolding will tend to experience tension. Further, the application of a load (e.g., due to the attachment of the food waste disposer 206) post-overmolding will tend to add tension or reduce compression within the improved mounting assembly 208. Therefore, the overall tension or compression experienced after a load is applied within the improved mounting assembly 208, and particularly by the springs 400, will depend upon the relative balance between any compression or tension that exists within the improved mounting assembly 208 prior to load being applied, the tension change imparted by the weight of the load itself.

The post-overmold states of the improved mounting assembly 208 shown in FIG. 8 exemplify these principles. More particularly, as shown, if the pre-load scenario experienced by the mounting subassembly 600/springs 400 involves a preset compression (scenario E), then the improved mounting assembly 208 will experience tension as its post-overmold state. The amount of tension will increase from a first level of tension occurring prior to a load being applied, due to the springs 400, to a second level of tension

occurring after the load has been applied (e.g., due to the attachment of the food waste disposer 206). By contrast, if the pre-load scenario experienced by the mounting subassembly 600/springs 400 involves no pre-load (scenario D), then the improved mounting assembly 208 will not experience any tension or compression as its post-overmold state, prior to a load being applied. However, the improved mounting assembly 208 will experience tension after the load has been applied (e.g., due to the attachment of the food waste disposer 206)—that is, the springs and annular elastomeric formation (e.g., TPE) will be in tension due to unit weight upon installation.

Further, if the pre-load scenario experienced by the mounting subassembly 600/springs 400 involves a preset tension (scenario C, B, or A), then the improved mounting assembly 208 will experience compression as its post-overmold state, as achieved at the fifth step 812 prior to the application of any load. The magnitude of the compression experienced in this state will correspond directly to the level of preset tension that was applied at the third step 808. However, upon the application of a load (e.g., due to the attachment of the food waste disposer 206) at the step 816, the improved mounting assembly 208 (and the springs 400 thereof) can experience any of compression, tension, or neither. It will be appreciated that, if the preset tension is sufficiently small (e.g., in accordance with scenario A of the first side-box 818), even though compression may be experienced by the TPE or other elastomeric material (or other material) initially after overmolding has been completed, any such compression will be superseded by the tension arising from the application of weight to the improved mounting assembly 208. Consequently, as indicated in the second side-box 820, the post-overmold states of the improved mounting assembly 208 associated with scenario A involve compression followed by tension arising due to the weight applied to the improved mounting assembly 208.

Inversely, it will be appreciated that, if the preset tension is sufficiently large (e.g., in accordance with scenario C of the first side-box 818), compression may be experienced by the TPE or other elastomeric material (or other material) initially after overmolding has been completed, and continue to be experienced following the application of the load to the improved mounting assembly 208. In such cases, the load borne by the improved mounting assembly 208 is insufficient to overcome the internal compression experienced by the improved mounting assembly 208 due to the internal action of the springs 400.

Additionally, there also exists the possibility that the application of the pre-load at the third step 808 is set at just an appropriate amount that any internal compression experienced by the improved mounting assembly 208 due to the internal action of the springs 400 can be exactly (or substantially exactly) balanced by the tension generated by a load borne by the improved mounting assembly 208. Thus, as illustrated in FIG. 8, if a particular “medium” preset tension is applied at the third step 808 (e.g., in accordance with scenario B), then compression may be experienced by the TPE or other elastomeric material (or other material) initially after overmolding has been completed at the fifth step 812, but then the improved mounting assembly 208 can experience an equilibrium between compression and tension following the application of the load at the step 816.

Thus, the various scenarios and states shown in FIG. 8 can be summarized as follows. If no pre-loading is applied, in accordance with Scenario D, then there will not be any post-overmold compression or tension experienced by the TPE (or other elastomeric or other material) until installation

of the food waste disposer occurs (e.g., when a load is applied) in accordance with the step 816. However, if pre-loading is applied in accordance with scenario A, the TPE (or other elastomeric or other material) will experience post-overmold compression due to the springs 400 and further, if the preset tension was small relative to the effect of unit weight, it would revert to tension upon installation of the food waste disposer (but less than if overmold in neutral state).

10 Further, if pre-loading is applied in accordance with scenario B and the preset was balanced against the effect of unit weight (e.g., the effect of the application of a load corresponding to installation of the food waste disposer), the TPE will experience post-overmold compression due to 15 springs, and further can end up in an equilibrium state (or a state that cycles through tension and compression during operation) upon installation of the food waste disposer. Also, if pre-loading is applied in accordance with scenario C, then TPE will experience post-overmold compression due to 20 springs and, if the preset was large relative to the effect of unit weight, the weight can be offset such that the TPE will remain in a state of compression (or mostly so, during operational cycling). Finally, if pre-loading is applied in accordance with scenario E, then TPE will experience 25 post-overmold tension due to springs, the state of which will be exacerbated by the addition of unit weight upon installation.

Notwithstanding the above description relating to FIG. 3, FIG. 4, FIG. 5, FIG. 6, FIG. 7, and FIG. 8 pertaining to the improved mounting assembly 208 of FIG. 2, it should be appreciated that the present disclosure is intended to encompass numerous other embodiments of improved mounting assemblies as well. For example, turning to FIG. 9, a perspective view of an alternate embodiment of an improved mounting assembly 908 is provided. It should be appreciated that the improved mounting assembly 908 can be implemented in a food waste disposer assembly that is identical or substantially identical to the food waste disposer assembly 200 of FIG. 2, except insofar as the improved mounting assembly 908 is intended to take the place of the improved mounting assembly 208 described above. As in the case of FIG. 3, FIG. 9 is particularly intended to show the improved mounting assembly 908 apart from the sink 202 and the food waste disposer 206, so as to highlight several features of the improved mounting assembly.

Similar to the improved mounting assembly 208, the improved mounting assembly 908 particularly includes an anti-vibration (AV) tube 910, an enclosure 912, and an overmolded section 914 positioned between and coupling the AV tube with the enclosure. The AV tube 910 is configured to be mounted or coupled to the sink flange (or strainer flange) 216 of the sink 202 (discussed above). The enclosure 912, which is positioned beneath the AV tube 910 and coupled therewith by way of the overmolded section 914, supports the food waste disposer 206, which is positioned beneath and coupled to that enclosure.

In the view provided by FIG. 9, the overmolded section 914 is visible. It should be appreciated that the overmolded section 914 takes the same (or substantially the same) position within the improved mounting assembly 908 as is taken by the overmolded section 214 within the improved mounting assembly 208, and fulfills the same (or substantially the same) role in the improved mounting assembly 908 as is fulfilled by the overmolded section 214 in the improved mounting assembly 208. Similar to the overmolded section 214, the overmolded section 914 particularly includes an annular elastomeric formation 900 extending between a

bottom circumferential lip 902 of the AV tube 910 and a top circumferential lip 904 of the enclosure 912. In addition as shown, the AV tube 910 also includes an additional top circumferential lip (or rim) 906, and is shown to extend upward from the bottom circumferential lip 902 to the top circumferential lip 906. As with the top circumferential lip 306 of FIG. 3, the top circumferential lip 906 particularly extends around and defines a top orifice of the AV tube 910, by way of which food waste can proceed into the food waste disposer assembly as described above.

As with the annular elastomeric formation 300, the annular elastomeric formation 900 can be made, for example, from a thermoplastic elastomer (TPE) or other elastomeric material. Also, as with the annular elastomeric formation 300, the annular elastomeric formation 900 serves an anti-vibration purpose, particularly in terms of eliminating or reducing the amount of vibration that can be communicated from the enclosure 912 to the AV tube 910, and thus in terms of eliminating or reducing the amount of vibration that can be communicated from the food waste disposer 206 of the disposer assembly 204 to the sink 202 when the disposer assembly 204 is coupled to the enclosure 912 and the AV tube 910 is coupled to the sink. However, it will be observed from a comparison of FIG. 9 relative to FIG. 3 that the overmolded section 914, and the annular elastomeric formation 900 thereof, differ respectively in shape from the overmolded section 214 and the annular elastomeric formation 300 thereof. More particularly, the overmolded section 914 and annular elastomeric formation 900 bulge radially outwardly at locations in between the bottom and top circumferential lips 902 and 904, unlike the overmolded section and annular elastomeric formation 300, which maintain a diameter that is substantially the same as the outer diameter of the bottom circumferential lip 302.

Referring additionally to FIG. 10 and FIG. 11, further views are provided of portions of the improved mounting assembly 908 in manners intended to reveal additional features of the overmolded section 914. FIG. 10 particularly provides a cutaway perspective view of portions of the improved mounting assembly 908, with bottom portions of the improved mounting assembly particularly being cutaway and the remaining illustrated portions being enlarged. The orientation of the improved mounting assembly 908, in terms of the perspective view shown, is the same as that of FIG. 9. FIG. 11 provides an additional detail view highlighting a portion of what is shown in FIG. 10.

More particularly with respect to FIG. 10 and FIG. 11, it should be recognized that, in addition to showing the annular elastomeric formation 900 extending between the AV tube 910 and the enclosure 912, the overmolded section 914 further includes multiple living-hinge members 1000 (one of which is shown in FIG. 11). As illustrated, the living-hinge members 1000 extend between the AV tube 910 and the enclosure 912. Further, in the present embodiment, all of the living-hinge members 1000 are integrally formed with the AV tube 910 and the enclosure 912. That is, the AV tube 210, enclosure 212, and the living-hinge members 1000 all are molded from a single piece of plastic material, which can (for example) be a polymer plastic material, and which is distinct from the material forming the annular elastomeric formation 900. Accordingly, the living-hinge members 1000, AV tube 210, and enclosure 212 can be considered to form a single integral mounting subassembly.

In the present example embodiment, there are two of the living-hinge members 1000, which are at diametrically-opposed locations from one another on the improved mounting assembly 908 (and of the AV tube 910 and enclosure 912

thereof). In alternate embodiments, the number or relative spacing of the living-hinge members 1000 can vary from that shown. For example, in other alternate embodiments, there can be three, four, six, or eight living-hinge members, and/or certain neighboring ones of the living-hinge members (particularly if there are more than two such members) can be positioned more closely to one another than other neighboring ones of the living-hinge members. Also, although it is envisioned that the improved mounting assembly 908 will include only living-hinge members and that the improved mounting assembly 208 will include only springs, in further embodiments it is possible for a given improved mounting assembly to include any combination of one or more springs and one or more living-hinge members.

As is evident particularly from FIG. 11, in the present embodiment each of the living-hinge members 1000 includes a plurality of indentations 1100 at several locations along the length of the respective member, at which the living-hinge member has reduced thickness and can easily bend (e.g., due to the relative narrowness of the living-hinge member at those locations). Each of the living-hinge members 1000, when positioned so as to be compressed somewhat between the AV tube 910 and the enclosure 912, takes a form as shown in FIG. 11 in which the respective living-hinge member has a respective first ramp portion 1104 and a respective second ramp portion 1106. As shown, the respective first ramp portion 1104 of the respective living-hinge member 1000 is integrally connected to the respective second ramp portion 1106 of the respective living-hinge member at a respective bend location or junction 1108. Such bending can for example be at angle(s) of less than 180 degrees.

More particularly, the respective first ramp portion 1104 of each of the respective living-hinge members 1000 extends from a respective circumferential location 1110 along the bottom circumferential lip 902 of the AV tube 910 toward the enclosure 912, to the respective junction 1108, and the respective second ramp portion 1106 of each respective living-hinge member 1000 extends from the respective junction to a respective circumferential location 1112 along the top circumferential lip 904 of the enclosure 912. Additionally as shown, the respective first ramp portion 1104 of each of the living-hinge members 1000 is generally inclined in a first radial direction (e.g., radially outward as one proceeds downward from the AV tube 910 toward the enclosure 912) and the respective second ramp portion 1006 of each of the living-hinge members 1000 is generally inclined in a second radial direction (e.g., radially outward as one proceeds upward from the enclosure 912 toward the AV tube 910).

It should be appreciated that the particular configurations of the living-hinge members 1000 as shown in FIG. 10 and FIG. 11, in which the living-hinge members 1000 are particularly experiencing bending at the junctions 1008 as well as proximate the circumferential locations 1110 and 1112 and in which portions of those living-hinge members between those junctions and locations take on the sloped form of the ramp portions 1104 and 1106, are not the natural (e.g., unstressed) configurations of those living-hinge members. Rather, the configurations of the living-hinge members 1000 shown in FIG. 10 and FIG. 11 are taken on by those living-hinge members particularly because the AV tube 910 and enclosure 912 are sufficiently close to one another that the living-hinge members are compressed between those structures.

Relatedly, it should be appreciated that, if the AV tube 910 and enclosure 912 are retracted apart from one another, the

living-hinge members will progressively straighten. Ultimately, when the distance between the AV tube **910** and enclosure **912** increases to equal the full length of the living-hinge members **1000**, each of the living-hinge members will have a configuration that is strictly linear between the respective circumferential locations **1110** and **1112** at which the respective living-hinge member is connected to the AV tube and enclosure. That is, in such circumstance, the living-hinge members **1000** will no longer have bending at or proximate to the junctions **1108** and circumferential locations **1110** and **1112**, and will not have sloped portions corresponding to the ramped portions **1104** and **1106**.

Additionally, it should be recognized from FIG. 10 and FIG. 11 that the living-hinge members **1000** (which are intended to be shown relative to the annular elastomeric formation **900** in a ghosted or phantom manner) are surrounded by and encapsulated (or substantially encapsulated) within the annular elastomeric formation **900**. That is, the annular elastomeric formation **900** is formed in relation to the AV tube **910**, the enclosure **912**, and the living-hinge members **1000** so as to extend between and fill in the gaps between the AV tube **910**, the enclosure **912**, and the living-hinge members **1000**. In particular, none of the living-hinge members **1000** is positioned radially outwardly, relative to the center line **1002** of the improved mounting assembly **908**, so as to extend radially outwardly beyond the annular elastomeric formation **900**. Rather, the annular elastomeric formation **900** by itself forms the outer circumference of the overmolded section **914**, including the living-hinge members **1000** thereof.

As with the springs **400**, it should be recognized that the living-hinge members **1000** provide a redundant coupling mechanism by which the AV tube **910** and enclosure **912** are linked, so as to supplement the coupling provided by the annular elastomeric formation **900**. That is, although it is intended that the annular elastomeric formation **900** serve as the primary support structure linking the AV tube **210** and the enclosure **212** in the improved mounting assembly **908**, the living-hinge members **1000** can serve a backup support structure. Consequently, although the annular elastomeric formation **900** will serve as the primary weight bearing structure allowing for any weight coupled to the enclosure **912** (e.g., the disposer assembly **204** with the food waste disposer **206**) to be borne by the AV tube **910** (and any structure supporting the improved food wasted disposer assembly **200** such as the sink **202**), the living-hinge members **1000** can also provide such support. This can be beneficial, for example, if over time the annular elastomeric formation **900** experiences creeping or becomes distended, or if for some reason the annular elastomeric formation itself ceases to fully or substantially couple the AV tube **910** with the enclosure **912** (for example, if adhesive used to link the annular elastomeric formation **900** with the AV tube or enclosure weakens).

The assembly or manufacturing process by which the improved mounting assembly **908** is formed can be similar to that discussed above in regard to FIG. 8. In particular, the assembly process will include a step corresponding to the first step **804**, at which a mounting subassembly including the AV tube **910**, enclosure **912**, and living-hinge members **1000** are integrally formed. Additionally, the assembly process will include a step corresponding to the fourth step **810**, at which application of an elastomer or overmolding occurs, so that the annular elastomeric formation **900** is provided and the overall improved mounting assembly **908** is formed. It should be mentioned that, although the living-hinge members (having reduced thickness) **1000** can have an included

angle of less than 180 degrees to reduce transmission of vibration and sound, but also the initial (as molded) support included angle may be altered during the elastomer overmolding process (to aid in processing). Following the overmolding, a post-overmolding state of the improved mounting assembly **908** is achieved, at a step corresponding to the fifth step **812** and, after this occurs, a load (such as the food waste disposer **206**) can be applied to the improved mounting assembly, at a step corresponding to the step **816**.

Notwithstanding the above similarities between the assembly processes for the improved mounting assemblies **908** and **208**, the steps of FIG. 8 relating to determining or applying pre-loading (e.g., the steps **806** and **808**), or achieving a post-overmolding state of the mounting assembly that may be influenced by such pre-loading, can be absent from the assembly process for the improved mounting assembly **908**. In the initial overmolded state, the living-hinge members **1000** typically will be bent as described above in regard to FIG. 10 and FIG. 11 (e.g., at the junctions **1108**). With such a bent configuration, the living-hinge members **1000** will not be significantly loaded in tension, and as a result will not transmit a significant amount of vibration between the enclosure **912** (and any structure coupled thereto, such as the food waste disposer **206**) and the AV tube **910**. However, given such a bent configuration and given that the living-hinge members **1000** are intended to be highly flexible in terms of such bending, the living-hinge members after being overmolded will impart little, if any, force with respect to the AV tube **910**, enclosure **912**, or annular elastomeric formation **900**. Thus, pre-loading as can be achieved way of the springs **400** is not generally achieved by way of the living-hinge members **1000**, and so little or no post-overmolding compression or tension offset effects are achieved via any such pre-loading relating to the living-hinge members **1000**.

The above-described embodiments relating to FIGS. 2 through 11 entail some example embodiments of improved mounting assemblies encompassed herein, in which backup support linkages are provided to supplement the coupling between an AV tube (such as the AV tubes **210** or **910**) and an enclosure (such as the enclosures **212** or **912**) that is afforded by way of an anti-vibration linkage (such as the annular elastomeric formations **300** or **900**). It will be appreciated that, in each of these above-described embodiments, the backup support linkages (whether in the form of the springs **400** or living-hinge members **1000**) are positioned radially-inwardly of the outer circumferences of the annular elastomeric formations **300** or **900** with which those springs or living-hinge members are substantially encapsulated. Nevertheless, the present disclosure is also intended to encompass embodiments having different arrangements as well, including arrangements in which the backup support linkages are positioned radially-outwardly of the outer circumferences of the annular elastomeric formations serving as the anti-vibration linkages.

More particularly in this regard, FIG. 12 shows a perspective view of an additional alternate embodiment of an improved mounting assembly **1208**. As with the improved mounting assembly **908**, the improved mounting assembly **1208** can be implemented in a food waste disposer assembly that is identical or substantially identical to the food waste disposer assembly **200** of FIG. 2, except insofar as the improved mounting assembly **1208** is intended to take the place of the improved mounting assembly **208** (or improved mounting assembly **908**) described above. As in the case of FIG. 3, FIG. 12 is particularly intended to show the improved mounting assembly **1208** apart from the sink **202**

and the food waste disposer 206, so as to highlight several features of the improved mounting assembly.

Similar to the improved mounting assembly 208, the improved mounting assembly 1208 particularly includes an anti-vibration (AV) tube 1210 and an enclosure 1212. Again, the AV tube 1210 is configured to be mounted or coupled to the sink flange (or strainer flange) 216 of the sink 202 (discussed above). Also, the enclosure 1212 is positioned beneath and coupled to the AV tube 1210, and supports the food waste disposer 206, which is positioned beneath and coupled to that enclosure. Additionally, the improved mounting assembly includes an annular elastomeric formation 1200 positioned between and coupling the AV tube 1210 with the enclosure 1212.

Notwithstanding these similarities, improved mounting assembly 1208 differs from the improved mounting assembly 208 in that the annular elastomeric formation 1200 is not overmolded around backup linkages (such as the springs 400 or living-hinge members 1000), but rather is simply an annular elastomer that is coupled to and extends between, and is in tension between, the AV tube 1210 and enclosure 1212. Rather than employing any backup linkages (such as the springs 400 or living-hinge members 1000) that are positioned within or substantially encapsulated within the annular elastomeric formation 1200, instead the improved mounting assembly 1208 includes two suspenders (or suspender extensions) 1214 on the AV tube 1210 and two complementary features 1216 on the enclosure 1212.

As shown, the suspenders 1214 particularly are extensions that are integrally formed or molded as part of the AV tube 1210, and coupled to the AV tube at locations along an outer circumference 1218 of the AV tube (in this example embodiment, along a bottom rim of the AV tube to which the annular elastomeric formation 1200 is coupled). The suspenders 1214 particularly extend downward from the AV tube 1210, in a manner substantially parallel to (in this example, tapered slightly relative to) a central axis 1202 of the improved mounting assembly 1208 and alongside the outer circumference of the annular elastomeric formation 1200, to the complementary features 1216 of the enclosure 1212. The complementary features 1216 and suspenders 1214 are configured so that the suspenders 1214 can be secured or attached to the complementary features 1216 during assembly of the improved mounting assembly 1208.

In the present embodiment, the complementary features 1216 particularly include orifices into which and through which the suspenders 1214 are positioned during assembly of the improved mounting assembly 1208. All of the AV tube 1210, suspenders 1214, enclosures 1212, and complementary features 1216 are made of a common, meltable material (e.g., polymer plastic). Given this to be the case, the suspenders 1214 can be coupled to or locked in relation to the complementary features 1216 by way of heating, melting, and cooling the suspenders and complementary features, or heat staking the suspenders and complementary features relative to one another. In alternate embodiments, other locking features (e.g., complementary teeth) can be provided on the suspenders and complementary features such that the suspenders become locked in place relative to the complementary features upon being inserted therein. Regardless of the manner in which suspenders are coupled to complementary features, the coupling of the suspenders with the complementary features should be performed in a manner that leaves some slack in the suspenders, so as to avoid overly restricting (e.g., in terms of extension) the annular elastomeric formation 1200.

The process of assembling the improved mounting assembly 1208 can particularly involve two steps, namely, the applying of an elastomer in relation to the AV tube 1210 and enclosure 1212 so as to couple those structures, and coupling the suspenders 1214 to the complementary features 1216, with those two steps being performable in a simultaneous or sequential (in either order) manner. Although not shown, for aesthetic purposes, the improved mounting assembly 1208 can be further supplemented with an additional cylindrical (or substantially cylindrical) trim shell component or skirt that is slipped over the AV tube 1210 and positioned so as to surround and cover over the suspenders 1214 and complementary features 1216. Implementation of such a trim shell component can be considered an additional step of assembly.

Also, notwithstanding the above description concerning the embodiment of FIG. 12, the present disclosure is intended to encompass alternate embodiments having features that differ from those described above. For example, in some alternate embodiments, the improved mounting assembly can include more than two suspenders and more than two complementary features. Also, in some alternate embodiments, the suspenders can be integrally formed or attached to the enclosure (bottom enclosure piece) and the complementary features can be provided on the AV tube (top enclosure piece). Additionally, although in some embodiments the suspenders can be molded into the AV tube (or alternatively the enclosure), in other embodiments the suspenders can be attached to the AV tube (or enclosure) by way of a drop-on harness that seats on a ledge on the AV tube (or top enclosure piece), from which the suspenders dangle, or the suspenders can be attached to the AV tube (or top enclosure piece) by way of a zip/stake operation. Further, in some alternate embodiments, suspenders or extensions can be integrally formed or connected to each of the AV tube and enclosure, and corresponding (circumferentially-aligned) ones of the suspenders extending from the AV tube and enclosure can be coupled with one another at locations in between the AV tube and enclosure (e.g., alongside the annular elastomeric formation).

In view of the above description, it should be appreciated that the present disclosure is intended to encompass numerous embodiments of improved mounting assemblies for implementation in food waste disposer assemblies or other disposer assemblies. In at least some embodiments encompassed herein, the improved mounting assemblies allow for the grind chamber of the waste disposer, or associated enclosure, to be isolated from the sink by the use of an intermediate band of material (such as rubber or a thermoplastic elastomer) at or immediately below the neck or tube which connects to the mounting assembly (e.g., the AV tube). By employing the intermediate band of material, the improved mounting assemblies provide an anti-vibration (AV) feature with a tensile load. In addition, the improved mounting assemblies include backup linkages such as, for example, springs, living-hinge members, or suspenders, that serve to support the waste disposer, and/or associated enclosure, relative to the AV tube and sink to which it is mounted. Thus, an AV tension mount can be achieved by providing substrate support that reduces, adjusts, or offsets the tensile loading on the elastomeric component of the mount, and/or provides back-up support.

In at least some such embodiments, the improved mounting assemblies can be considered spring overmold-mount assemblies that (a) employ spring members to join the AV tube and enclosure to act with an overmold as a spring-and-elastomer suspension and damping system, and (b) optionally also involve pre-loading during the overmolding pro-

cess to achieve an optimized in-service loading for the mount. That is, in at least some embodiments, a set of integral springs connects, and is molded together with, the AV tube and the enclosure. This mounting subassembly or substrate structure is then overmolded together with an elastomeric material (or other material), such as a thermoplastic elastomer (TPE). The springs provide backup support in terms of the coupling of the enclosure—and structure(s) attached thereto, such as a food waste disposer—to the AV tube (and therefore to the sink or any other structure to which the AV tube is attached). The substrate springs would optionally allow a pre-load (in tension or compression) to be applied at the time of the overmolding process. This permits the TPE or other overmold material to be influenced with regard to its loading during post-installation service, with the potential to offset at least some of a food waste disposer or other unit's weight or achieve an optimal state for performance and structural integrity. Depending upon the embodiment, the geometries and number of springs can be set or iterated to optimize the anti-vibration performance of the spring-overmold mount.

Also, in at least some other embodiments, multiple sets of living-hinge members (or living hinges with reduced thickness) and rigid member pairs connect, and are molded together with, the AV tube and the enclosure. That combined subassembly (and particularly the living-hinge members) are then overmolded with an elastomeric material or other material (such as TPE). The overmolding is performed in a manner such that the living-hinge members are not significantly loaded in tension and will not transmit a significant amount of vibration, yet provide back-up support for the AV mount to reduce or eliminate disadvantages that can arise if the elastomeric material creeps in tension. Again, the geometry of these living-hinge members (as with the springs discussed above or other substrate members), including their orientation/loading during the overmolding process, or both, can be iterated or adjusted to optimize the AV performance and the forces acting on the elastomeric mount feature.

Further, in at least some additional embodiments, the improved mounting assemblies employ external-support alternatives. Such improved mounting assemblies again can include an annular elastomeric formation or other structure that links the AV tube and enclosure and is intended to prevent or reduce the amount of vibration communicated between the AV tube and enclosure, and can again include backup linking structures that couple, and are integrally formed or molded in relation to, one or both of the AV tube and enclosure. However in contrast to embodiments in which springs, living hinges, or other backup linking structures connecting the AV tube and enclosure are positioned or substantially encapsulated within an overmolded structure, the backup linking structures in such external-support alternatives are positioned radially outward and/or radially inward (or otherwise externally) from the location of any annular elastomeric formation or other structure formed from an elastomeric (or other) material that links the AV tube and the enclosure. For example, such external-support alternatives can employ, as the backup linking components (or backup support linkages), suspenders (and possibly complementary features) that are integrally formed in relation to one or both of the AV tube and the enclosure. Also for example, depending upon the embodiment, the backup linking structures can be offset relative to, or in-line with, areas where a substrate wall is already produced by existing tooling.

As already discussed in regard to FIG. 12, in some such external-support alternatives, backup linking components

are positioned radially outward of an annular elastomeric formation (e.g., alongside, or spaced-apart from but proximate to, an outer circumference of the annular elastomeric formation)—as in the case of the suspenders 1214 extending downward alongside the outer circumference of the annular elastomeric formation 1200 of the improved mounting assembly 1208. However, in some other external-support alternatives, backup linking components such as suspenders, springs, or living-hinge members are positioned radially inward of such an annular elastomeric formation (e.g., alongside, or spaced-apart from but proximate to, an inner circumference of the annular elastomeric formation)—in such embodiments, the elastomer is radially outward of the backup linking components (or linking structures) without substantially encapsulating them. To achieve such an arrangement, and particularly the desired elastomeric formation in such an arrangement, the shutting off of the formation of the overmold on the inside can in some cases be achieved by way of a collapsing core on the overmold tool. Further, to avoid or reduce the potential for entrapment of food particles or other material along/within the backup linking components, in some cases a secondary sleeve or insert can be positioned along or near those backup linking components. For example, in some such cases, such a secondary sleeve or insert can be heat staked to the AV tube above the backup linking components and hang down past the backup linking components in the form of a shield or curtain (e.g., hang down radially inward of the backup linking components such that the backup linking components are radially in between such a shield or curtain and the annular elastomeric formation), so as to prevent or reduce the entry of food debris or other material to the locations of the backup linking components.

Additionally, the present disclosure is also intended to encompass other embodiments employing one or more other types of linking structures for coupling an AV tube and enclosure that are positioned externally of an annular elastomeric formation or similar structure serving as an anti-vibration link between the AV tube and enclosure, including for example, springs or rods. Such additional linking structures can for example be employed in combination with any of the suspenders, springs, living hinges, or other backup linking structures described above. For example, in some embodiments encompassed herein, an AV tube and enclosure are coupled by one or more backup linking structures that are overmolded (such as the springs 400 or living-hinge members 1000) and additionally by one or more other backup linking structures that are externally positioned relative to any annular elastomeric formation or other anti-vibration coupling structure.

Turning to FIG. 13, a cross-sectional view is provided of an additional example improved food waste disposer assembly 1300 having an improved mounting assembly 1308, where the cross-section is taken along a central axis 1312 of the improved food waste disposer assembly (where, in the present embodiment, the central axis is vertically-oriented). In this embodiment, the improved food waste disposer assembly 1300 includes each of a top enclosure piece or neck (which also can be considered an AV tube or tubular structure) 1310, an AV tension mount 1302, a trim shell assembly 1304, and a food waste disposer 1306. Also in the present embodiment, the improved mounting assembly 1308 particularly can be understood to include the top enclosure piece or neck 1310, the AV tension mount 1302, and portions of the trim shell assembly 1304 and the food waste disposer 1306 as described in further detail below. Additionally, although not shown, the improved food waste disposer

assembly 1300 can be installed relative to (e.g., beneath) a sink such as the sink 202 described above, with the top enclosure piece 1310 being mounted or coupled to a sink flange assembly of the sink (e.g., to the sink flange assembly 216 of the sink 202 of FIG. 2). The top enclosure piece 1310 can be mounted or coupled to the sink flange assembly of the sink by coupling components (e.g., the coupling components 215 of FIG. 2), which also can be considered to form part(s) of the improved mounting assembly 1308.

In the present example embodiment, the trim shell assembly 1304 includes an upper trim shell portion 1314 and a lower trim shell portion 1316, where the lower trim shell portion has generally the shape of a bowl including a tapered cylindrical wall 1318 integrally formed with a bottom wall 1320 and the upper trim shell portion has the shape of an inverted bowl including a cylindrical wall 1322 integrally formed with a top wall 1324 having an orifice 1326 defined by an inwardly-facing rim 1328 within the top wall 1324. The lower trim shell portion 1316 interfaces, and is secured to, the upper trim shell portion 1314 along a junction 1330 formed between an upper rim of the cylindrical wall 1318 of the lower trim shell portion, and a lower rim of the cylindrical wall 1322 of the upper trim shell portion. In the present embodiment, the trim shell assembly 1304 generally surrounds and encloses the food waste disposer 1306, except for the orifice 1326 formed within the top wall 1324 and one or more other orifices formed in the trim shell assembly (not shown), by which the food waste disposer can, for example, output food waste and water, or receive water from another source, such as a dishwasher, or receive power.

In the present example embodiment, the food waste disposer 1306 includes a food conveying section 1332, a motor section 1334, and a grinding section 1336 disposed between the food conveying section and the motor section. Also, the food waste disposer 1306 includes an upper enclosure or housing portion 1338 and a lower enclosure or housing portion 1340, which can also be referred to as a stator ring. In the present embodiment, the upper enclosure 1338 houses (or defines or surrounds) the food conveying section 1332 and the grinding section 1336, and the lower enclosure 1340 houses (or defines or surrounds) the motor section 1334. The lower enclosure 1340 generally has the shape of a bowl including a cylindrical wall 1348 integrally formed with a bottom wall or lower end frame (LEF) 1346 and the upper enclosure 1338 has the shape of a cylinder that tapers inwardly as one proceeds upward from a bottom rim 1342 to a top rim 1344. The lower enclosure 1340 interfaces and is secured to the upper enclosure 1338 along a junction between an upper rim of the cylindrical wall 1348 and the bottom rim 1342 of the upper enclosure. In the present embodiment, the bottom wall 1346 of the lower enclosure 1340 of the food waste disposer 1306 is merely adjacent to and (at least in some circumstances) in contact with the bottom wall 1320 of the lower trim shell portion 1316 of the trim shell assembly 1304. However, in alternate embodiments, the bottom wall 1346 and bottom wall 1320 can be coupled or linked with one another.

It should be appreciated that all or a portion of the trim shell assembly 1304 serves as an enclosure structure or housing for the food waste disposer 1306. Also, it should be appreciated that a generally annular space 1360 exists within the trim shell assembly 1304 (especially the upper trim shell portion 1314), between inner surfaces of the trim shell assembly and outer surfaces of the food waste disposer 1306 (especially the upper enclosure 1338). The annular space 1360 can be filled with air or with a sound insulating material that prevents or reduces the communication of

noise from the food waste disposer 1306, when operating, to and out of the trim shell assembly 1304. Also it should be appreciated that the top rim 1344 of the upper enclosure 1338 defines an inlet (or orifice) 1350 of the food conveying section 1332 by which the food conveying section can receive food waste and water. The food conveying section 1332 conveys the food waste and water to the grinding section 1336, and the motor section 1334 includes a motor 1352 imparting rotational movement to a motor shaft 1354 to operate the grinding section, particularly by causing rotation of a shredder plate 1356 of the grinding section relative to a shredder ring 1358. Upon being acted upon by the grinding section 1336, the food waste and water can pass from that grinding section out from the food waste disposer 1306 via an outlet (not shown).

Notwithstanding the above description of the food waste disposer 1306, the present disclosure is intended to encompass a wide variety of embodiments. For example, even though the grinding section 1336 in the embodiment of FIG. 13 is housed within the upper enclosure 1338 rather than the lower enclosure 1340, the present disclosure is also intended to encompass other embodiments in which the grinding section is housed with the lower enclosure rather than the upper enclosure. Indeed, the present disclosure encompasses numerous other embodiments of food waste disposers, as well as other types of waste disposers (including waste disposers that are suited for disposing of other materials rather than food) as well as waste disposers that are to be mounted in relation to other types of structures instead of sinks.

FIG. 13 particularly shows the improved food waste disposer assembly 1300 when that assembly, and/or the improved mounting assembly 1308 thereof, is or are in a normal operational state. In this state, it can be appreciated that both the trim shell assembly 1304 and the food waste disposer 1306 are coupled to, and supported beneath, the top enclosure piece 1310 (and thus indirectly relative to the sink) by the AV tension mount 1302. That is, a combination structure 1311 including both the trim shell assembly 1304 and the food waste disposer 1306 is coupled to, and supported beneath, the top enclosure piece 1310 (and thus indirectly relative to the sink) by the AV tension mount 1302 (further, depending upon the context, such a combination structure 1311 can be referred to as a food waste disposer or food waste disposer assembly that includes the trim shell assembly). In particular, a top rim portion 1362 of the AV tension mount 1302 is coupled to, and supported beneath, the top enclosure piece 1310, and each of the trim shell assembly 1304 and the food waste disposer 1306 are coupled to, or rest upon, a bottom rim portion 1364 of the AV tension mount. The AV tension mount 1302 in the present embodiment is an annular elastomeric member or structure formed from TPE or other elastomeric material. The AV tension mount 1302 serves to prevent or reduce the communication of vibration from the food waste disposer 1306, as can be received at the bottom rim portion 1364 either directly from the food waste disposer or from the trim shell assembly 1304, to the top enclosure piece 1310 and thus to the sink during operation of the food waste disposer.

Referring additionally to FIG. 14, a detail, cutaway, perspective view of a portion 1400 of the improved food waste disposer assembly 1300 of FIG. 13 is shown. FIG. 14 further illustrates the manner in which the trim shell assembly 1304, food waste disposer 1306, and top enclosure piece 1310 are all coupled with the AV tension mount 1302 when the improved food waste disposer assembly 1300 (or improved mounting assembly 1308 thereof) is in the normal

operational state. FIG. 14 particularly shows that the top rim 1344 of the upper enclosure 1338 of the food waste disposer 1306 includes an annular lip 1402 that extends upward and into a complementary annular notch 1404 formed within (extending upward into) the bottom rim portion 1364 of the AV tension mount 1302, such that the upper enclosure of the food waste disposer is coupled to and supported beneath the AV tension mount. Additionally, FIG. 14 also shows that a bottom rim 1406 of the top enclosure piece 1310 includes an annular lip 1408 that extends downward and into a complementary annular notch 1410 formed within (extending downward into) the top rim portion 1362 of the AV tension mount 1302, such that AV tension mount is coupled to and supported beneath the top enclosure piece 1310.

Further, FIG. 14 additionally shows that the upper trim shell portion 1314 of the trim shell assembly 1304 additionally includes an annular wall 1412 that is integrally formed with, and extends downwardly from, the top wall 1324. The annular wall 1412 has a radial extent (relative to the central axis 1312 as shown in FIG. 13) that is greater than that of the inwardly-facing rim 1328 defining the orifice 1326, but less than that of the cylindrical wall 1322 of the upper trim shell portion 1314. The annular wall 1412 particularly extends downwardly to a bottom annular edge 1414. As shown, the bottom annular edge 1414 is positioned within a complementary annular notch 1416 that is also formed within an upwardly-facing surface 1418 of a radially-outermost edge portion 1420 of the bottom rim portion 1364 of the AV tension mount 1302, such that the annular wall 1412 (and the trim shell assembly 1304 overall) can be said to be supported upon the bottom rim portion 1364. Because the AV tension mount 1302 has a diameter that varies between the top rim portion 1362 and the bottom rim portion 1364, and that is greatest at the location of the bottom rim portion 1364, the annular wall 1412 generally is positioned radially outward around the AV tension mount 1302 as the annular wall proceeds from the top wall 1324 to the bottom annular edge 1414, except where the bottom annular edge 1414 interfaces and proceeds into the complementary annular notch 1416.

Given this arrangement shown in FIG. 13 and FIG. 14, it should be appreciated that, when the improved food waste disposer assembly 1300 (or improved mounting assembly 1308 thereof) is in the normal operational state as shown, the trim shell assembly 1304 and food waste disposer 1306 are fully supported relative to the top enclosure piece 1310 by the AV tension mount 1302, insofar as both the trim shell assembly and food waste disposer are coupled to the AV tension mount (which in turn is coupled to the top enclosure piece). More particularly, the food waste disposer 1306 is coupled to, and supported in relation to, the bottom rim portion 1364 of the AV tension mount 1302 due to the interfacing of the annular lip 1402 of the top rim 1344 of the upper enclosure 1338 of the food waste disposer 1306 and the complementary annular notch 1404 formed within the bottom rim portion 1364 of the AV tension mount 1302. Further, the trim shell assembly 1304 is coupled to, and supported in relation to, the bottom rim portion 1364 of the AV tension mount 1302 due to the positioning and supporting of the bottom annular edge 1414 of the annular wall 1412 within the complementary annular notch 1416 of the bottom rim portion 1364. Relatedly, in the present embodiment, the trim shell assembly 1304 (including the annular wall 1412) and food waste disposer 1306 are configured (e.g., sized) so that the bottom wall 1346 of the lower enclosure 1340 of the food waste disposer is in contact with (and can be considered to rest upon) the bottom wall 1320

of the lower trim shell portion 1316 of the trim shell assembly. Also, in the present embodiment, the bottom rim portion 1364 of the AV tension mount 1302 can be considered to be positioned and held between the bottom annular edge 1414 (of the annular wall 1412 of the upper trim shell portion 1314) of the trim shell assembly 1304 and the top rim 1344 (including the annular lip 1402) of the upper enclosure 1338 of the food waste disposer 1306.

Although FIG. 13 and FIG. 14 show the food waste disposer assembly 1300 in the normal operational state, it is possible that in some circumstances (e.g., after a long period of use) the AV tension mount 1302 may become elongated in terms of the distance between the top rim portion 1362 (or top surface thereof) and the bottom rim portion 1364 (or bottom surface thereof) by comparison with what is shown in FIG. 13 and FIG. 14. This can occur, for example, if the AV tension mount 1302 experiences creeping or becomes distended. Indeed, it is possible that, in some circumstances, the AV tension mount 1302 may even break or rupture such that the bottom rim portion 1364 is partly or entirely physically decoupled from the top rim portion 1362. If such a break or rupture occurred, it might no longer be possible for the trim shell assembly 1304 and food waste disposer 1306 to be fully supported in relation to the top enclosure piece 1310 by the AV tension mount 1302. Nevertheless, in the present embodiment, even if a break or rupture occurs with respect to the AV tension mount 1302, the trim shell assembly 1304 and food waste disposer 1306 will still be fully supported in relation to the top enclosure piece.

In particular, it should be appreciated that, as shown in FIG. 14, the inwardly-facing rim 1328 within the top wall 1324 (of the upper trim shell portion 1314) of the trim shell assembly 1304 has a diameter that is smaller than an outer diameter of the bottom rim 1406 of the top enclosure piece 1310 (e.g., relative to the central axis 1312 shown in FIG. 13). Further, FIG. 14 also illustrates that a gap 1422 exists between a bottom surface 1424 of the top wall 1324 (of the upper trim shell portion 1314) of the trim shell assembly 1304 and a top surface 1426 of the bottom rim 1406 of the top enclosure piece 1310 when the food waste disposer assembly 1300 (or mounting assembly 1308 thereof) is in the normal operational state. In view of these considerations, it should be recognized that, if the AV tension mount 1302 stretches or becomes elongated such that the distance between the bottom rim portion 1364 (or bottom surface thereof) and the top rim portion 1362 (or top surface thereof) increases from what is shown in FIG. 13 and FIG. 14, correspondingly the gap 1422 existing between the bottom surface 1424 of the top wall 1324 and the top surface 1426 of the bottom rim 1406 will decrease in size or length. More particularly, as the bottom rim portion 1364 moves away from the top rim portion 1362, the annular wall 1412 supported upon that bottom rim portion will also experience corresponding movement, as will the top wall 1324, such that the top wall 1324 will approach the top surface 1426 of the bottom rim 1406.

Further, if the AV tension mount 1302 becomes sufficiently elongated, or breaks or ruptures, the distance between the bottom rim portion 1364 and the top rim portion 1362 will become sufficiently great that the top wall 1324 of the trim shell assembly 1304 will move toward the bottom rim 1406 of the top enclosure piece 1310 until the bottom surface 1424 of the top wall 1324 proximate the inwardly-facing rim 1328 comes to rest upon the top surface 1426 of the bottom rim 1406 of the top enclosure piece 1310. In such circumstance, the improved food waste disposer assembly 1300 and/or the improved mounting assembly 1308 thereof

can be understood to be in an alternative backup support state (in contrast to the normal operational state shown in FIG. 13 and FIG. 14). When the improved food waste disposer assembly 1300 is in the alternative backup support state, the gap 1422 will no longer be present between the bottom surface 1424 and the top surface 1426 (that is, the gap will have become zero), and the entire trim shell assembly 1304 will be supported upon the top enclosure piece 1310 due to the contact between the top wall 1324 of the trim shell assembly and the bottom rim 1406 of the top enclosure piece. Additionally, even if the food waste disposer 1306 is not supported (or only partly supported) in relation to the top enclosure piece 1310 by the AV tension mount 1302 due to the AV tension mount being ruptured, broken, or elongated so as to provide less tension than when in the normal operational state, the food waste disposer 1306 will still be supported in relation to the top enclosure piece 1310. Indeed, in this circumstance, the food waste disposer will be supported within and by the trim shell assembly 1304 (e.g., due to contact of the bottom wall 1346 and the bottom wall 1320). Thus, due to the contact between the top wall 1324 and the bottom rim 1406, the entire combination structure 1311 of the trim shell assembly 1304 and the food waste disposer 1306 will continue to be supported by and in relation to the top enclosure piece 1310 and thus in relation to any sink beneath which the improved food waste disposer assembly 1300 is positioned.

In view of the above description, it should be appreciated that the improved food waste disposer assembly 1300 and improved mounting assembly 1308 thereof can be viewed as having a primary support mechanism provided by the AV tension mount 1302 and a secondary or backup support mechanism provided by the combination of the top wall 1324 and the bottom rim 1406. The primary support mechanism provided by the AV tension mount 1302 can be referred to as a “belt,” and the secondary (or backup) support mechanism provided by the combination of the top wall 1324 and the bottom rim 1406 (or modified versions of such features) can be referred to as a “suspender” or “suspenders,” such that the overall combination of those primary and secondary support mechanisms can be referred to as a “belt and suspenders” arrangement.

It should also be appreciated that the improved mounting assembly 1308 can be understood as having a purpose of supporting the combination structure 1311 including both the trim shell assembly 1304 and the food waste disposer 1306 relative to the top enclosure piece 1310 (and thus in relation to any sink), or alternatively as having a purpose of supporting particularly the food waste disposer 1306 relative to the top enclosure piece 1310 (and thus in relation to any sink). To the extent that the purpose of the improved mounting assembly 1308 is understood in the latter manner—that is, to the extent the purpose of the improved mounting assembly 1308 is to support the food waste disposer 1306 in particular—in that context the entire trim shell assembly 1304 (and not merely the top wall 1324 thereof) can be considered to form part of the improved mounting assembly 1308 and the secondary (or backup) support mechanism. That is, in such context, when the improved food waste disposer assembly 1300 is in the alternative backup support state, the entire trim shell assembly 1304 will contribute to the supporting of the food waste disposer 1306 therewithin due to the contact between the bottom wall 1346 of the food waste disposer and bottom wall 1320 of the trim shell assembly, and thus can be considered to constitute part of the improved mounting assembly 1308.

The secondary (or backup) support mechanism provided by the combination of the top wall 1324 and the bottom rim 1406 of FIG. 13 and FIG. 14 (or modified versions of such features as provided in some alternative embodiments or in other contexts) differ from some of the embodiments described herein in regard to FIGS. 2 through 12. Indeed, in contrast with one or more of the springs, living-hinge members, or suspenders (or other backup linking structures) described above in regard to FIGS. 2 through 12 herein, the secondary (or backup) support mechanism of FIG. 13 and FIG. 14 does not include structures that are integrally coupled with both of, or that otherwise physically connect or link, a structure such as the top enclosure piece 1310 with the food waste disposer 1306 (or with the combination structure 1311 or the trim shell assembly 1304). Nevertheless, the secondary (or backup) support mechanism provided by the combination of the top wall 1324 and the bottom rim 1406 (or modified versions of such backup support features as provided in some alternative embodiments or in other contexts) can still serve to reduce, adjust, or offset the tensile loading on the AV tension mount 1302 (or other elastomeric components) and/or provide backup support in some circumstances, such as when the improved food waste disposer assembly 1300 is in the alternative backup support state.

Indeed, the secondary (or backup) support mechanism of FIG. 13 and FIG. 14, including the top wall 1324 and bottom rim 1406 as backup support features, enables the trim shell assembly 1304 and the food waste disposer 1306 to be supported relative to the top enclosure piece 1310 when the AV tension mount 1302 is unable, by itself or unilaterally, to provide a desired support level of the trim shell assembly and the food waste disposer relative to the top enclosure piece. That is, when the improved food waste disposer assembly 1300 (and associated improved mounting assembly 1308) is in the normal operational state, the AV tension mount 1302 is able, by itself or unilaterally, to provide a tension force constituting a desired support level in that the tension force is sufficient to maintain the trim shell assembly 1304 and food waste disposer 1306 in position, or substantially in position, relative to the top enclosure piece 1310 as shown in FIG. 13 and FIG. 14, such that the gap 1422 (or at least some gap or space) is present between the top wall 1324 and the bottom rim 1406. In that circumstance, the AV tension mount 1302 is able, by itself or unilaterally, to provide a tension force that is sufficient to prevent one or both of the trim shell assembly 1304 and food waste disposer 1306 from experiencing a positional change relative to the tubular structure that is equal to or greater than the distance shown as the gap 1422. However, when the improved food waste disposer assembly 1300 (and associated improved mounting assembly 1308) is no longer in the normal operational state but rather enters the alternative backup support state, the AV tension mount 1302 is unable, by itself or unilaterally, to provide a tension force that is sufficient to maintain any gap or space between the top wall 1324 and the bottom rim 1406, and so is unable to provide the desired support level. In that circumstance, the top wall 1324 comes into contact with and is supported by the bottom rim 1406, such that backup support for the trim shell assembly 1304 and food waste disposer 1306 is provided.

Notwithstanding the embodiment described above in regard to FIG. 13 and FIG. 14, the present disclosure also encompasses other embodiments of improved food waste disposer assemblies and improved mounting assemblies that have other or additional features. For example, although in the embodiment of FIG. 13 and FIG. 14 each of the inwardly-facing rim 1328 of the top wall 1324 of the trim

shell assembly 1304 and the bottom rim 1406 (and particularly the top surface 1426 thereof) is fully annular, it should be appreciated that this need not be the case in all embodiments. For example, in some alternate embodiments, the top wall 1324 can include two or more (typically at least three more) radially-inwardly extending protrusions that extend radially-inward toward the central axis 1312 from the location of the annular wall 1412. In such embodiments, if the AV tension mount 1302 becomes sufficiently elongated, or breaks or ruptures, the distance between the bottom rim portion 1364 and the radially-inwardly extending protrusions of the top wall will become sufficiently great that those radially-inwardly extending protrusions will move toward the bottom rim 1406 of the top enclosure piece until those radially-inwardly extending protrusions come to rest upon the top surface 1426 of the bottom rim 1406 of the top enclosure piece.

Also for example, in some alternate embodiments, an improved food waste assembly can employ an improved mounting assembly that employs combinations of the various backup support linkages and/or secondary (or backup) support mechanisms described herein. Further for example in this regard, in some embodiments, an improved food waste disposer assembly can include each of an AV tension mount (or overmolded section or elastomeric formation) that couples each of a top enclosure piece such as the top enclosure piece 1310 with a combination structure including both a food waste disposer and a trim shell assembly, in which there are both first and second secondary (or backup) support mechanisms. That is, in some such embodiments, the improved mounting assembly includes both a first secondary (or backup) support structure having one or more of the springs, living-hinge members, or suspenders (or other backup linking structures) such as any of those described in regard to FIGS. 2 through 12 herein, and also a top wall on a trim shell assembly that is configured to contact and rest upon a bottom rim portion of the top enclosure piece 1310 in the event that the AV tension mount becomes overly-elongated, or ruptures or breaks.

Referring additionally to FIG. 15, FIG. 16, and FIG. 17, the present disclosure encompasses numerous other embodiments of food waste disposer assemblies with improved mounting assemblies in which a backup support mechanism is provided to supplement an annular elastomeric formation (or AV tension mount). In at least some such embodiments, the improved mounting assemblies serve to support a bottom enclosure piece associated with a food waste disposer, which can be positioned beneath and coupled to that bottom enclosure piece, in relation to a top enclosure piece or neck, which can be configured to be mounted or coupled to a sink flange or strainer flange (and thus to a sink). In at least some such embodiments, the improved mounting assembly includes two or more backup linking structures that extend between a top rim portion of the bottom enclosure piece and a bottom rim portion of the top enclosure piece. Further, in at least some such embodiments, the backup support mechanism particularly provides support of the bottom enclosure piece (and associated food waste disposer) relative to the top enclosure piece (and thus to a sink) when the annular elastomeric member is unable, by itself or unilaterally, to provide a desired support level.

More particularly in this regard, FIG. 15 and FIG. 16 respectively show perspective views of cutaway portions of further examples of improved mounting assemblies, namely, an improved mounting assembly 1508 and an improved mounting assembly 1608. As with the improved mounting assembly 1208, each of the improved mounting assemblies

1508 and 1608 can be implemented in a food waste disposer assembly that is identical or substantially identical to the food waste disposer assembly 200 of FIG. 2, except insofar as each respective improved mounting assembly 1508 or 1608 is intended to take the place of the improved mounting assembly 208 (or improved mounting assembly 1208) described above. As in the case of FIG. 12, each of FIG. 15 and FIG. 16 is particularly intended to show the respective further improved mounting assembly 1508 or 1608 apart from the sink 202 and the food waste disposer 206, so as to highlight several features of the respective improved mounting assembly.

Similar to the improved mounting assembly 1208, each of the improved mounting assemblies 1508 and 1608 particularly includes a top enclosure piece or neck (or anti-vibration (AV) tube) 1510 or 1610, respectively, and a bottom enclosure piece 1512 or 1612, respectively. Again, each respective top enclosure piece 1510 or 1610 is configured to be mounted or coupled to the sink flange (or strainer flange) 216 of the sink 202 (discussed above). Also, each respective bottom enclosure piece 1512 or 1612 is positioned beneath and coupled to the respective top enclosure piece 1510 or 1610, respectively, and supports the food waste disposer 206 (not shown in FIG. 15 and FIG. 16, but see FIG. 2), which is positioned beneath and coupled to that respective bottom enclosure piece. Additionally, each of the improved mounting assemblies 1508 and 1608 includes a respective AV tension mount (or annular elastomeric formation) 1500 or 1600, respectively, which is respectively positioned between and couples the respective top enclosure piece 1510 or 1610, respectively, with the respective bottom enclosure piece 1512 or 1612, respectively.

Similar to the embodiment of FIG. 13 and FIG. 14 in which the improved mounting assembly 1308 includes the bottom rim 1406 of the top enclosure piece 1310, the improved mounting assemblies 1508 and 1608 respectively include bottom rim portions 1564 and 1664, respectively, of the respective top enclosure pieces 1510 and 1610, respectively. The respective bottom rim portions (or ledges) 1564 and 1664 can be integrally formed as parts of the top enclosure pieces 1510 and 1610, respectively, or alternatively can be distinct components that are coupled to those top enclosure pieces, respectively. Also, similar to the embodiment of FIG. 13 and FIG. 14 in which the improved mounting assembly 1308 includes the top wall 1324, the improved mounting assemblies 1508 and 1608 respectively include top rim portions 1562 and 1662, respectively, of the respective bottom enclosure pieces 1512 and 1612, respectively. The respective top rim portions (or ledges) 1562 and 1662 can be integrally formed as parts of the bottom enclosure pieces 1512 and 1612, respectively, or alternatively can be distinct components that are coupled to those bottom enclosure pieces, respectively. The respective bottom and top rim portions 1564 and 1562 of the improved mounting assembly 1508 can be considered parts of the backup support mechanism of that improved mounting assembly, and likewise the respective bottom and top rim portions 1664 and 1662 of the improved mounting assembly 1608 can be considered parts of the backup support mechanism of that improved mounting assembly.

Additionally, in the present embodiments, the respective backup support mechanisms of the improved mounting assemblies 1508 and 1608 include respective backup linking structures (or backup support linkages/backup linkages) 1560 and 1660, respectively. The backup linking structures 1560 extend between the bottom rim portion 1564 of the top enclosure piece 1510 and the top rim portion 1562 of the

bottom enclosure piece 1512 of the improved mounting assembly 1508, and the backup linking structures 1660 extend between the bottom rim portion 1664 of the top enclosure piece 1610 and the top rim portion 1662 of the bottom enclosure piece 1612 of the improved mounting assembly 1608. In the present embodiment, the improved mounting assembly 1508 is shown to include two of the backup linking structures 1560 and the improved mounting assembly 1608 is shown to include two of the backup linking structures 1660. Nevertheless, depending upon the embodiment, any arbitrary number of the backup linking structures 1560 can be present in the improved mounting assembly 1508 (albeit typically two or more than two are present), and likewise any arbitrary number of the backup linking structures 1660 can be present in the improved mounting assembly 1608 (albeit typically two or more than two are present).

More particularly, in the improved mounting assembly 1508 of FIG. 15, the backup linking structures 1560 particularly include a first backup linking structure 1572 and a second backup linking structure 1574. In this embodiment, each of the first and second backup linking structures 1572 and 1574 includes a respective rod (or rod suspender) portion 1576 extending between a respective top cap (or head or nut) 1578 and a respective bottom cap (or head or nut) 1580 (of which only one is visible on FIG. 15). Each of the respective rod portions 1576 extends particularly through a respective upper hole 1582 formed within the bottom rim portion 1564 of the top enclosure piece 1510 (only one of which is visible in FIG. 15) and a respective lower hole 1584 formed within the top rim portion 1562 of the bottom enclosure piece 1512. Thus, the respective top cap 1578 of each of the first and second backup linking structures 1572 and 1574 is positioned above the bottom rim portion 1564, and the respective bottom cap 1580 of each of the first and second backup linking structures is positioned below the top rim portion 1562. The respective top caps 1578 and respective bottom caps 1580 are respectively coupled to the respective rod portions 1576 and are sized so that the respective top caps and respective bottom caps cannot pass through the respective upper holes 1582 and respective lower holes 1584, such that the rod portions are precluded from passing out of those upper and lower holes. The respective first and second backup linking structures 1572 and 1574 are also located at different circumferential locations around the respective bottom rim portion 1564 and top rim portion 1562.

FIG. 15 particularly shows the improved mounting assembly 1508 when in a normal operational state such that the bottom enclosure piece 1512 (and associated food waste disposer) is fully supported relative to the top enclosure piece 1510 (and sink) by the AV tension mount 1500. FIG. 15 additionally shows that, in the present embodiment, each of the rod portions 1576 of the first and second backup linking structures 1572 and 1574 has a length that is longer than the distance separating the bottom rim portion 1564 from the top rim portion 1562 (e.g., the distance separating a top surface of the bottom rim portion 1564 from a bottom surface of the top rim portion 1562) when the improved mounting assembly 1508 is in the normal operational state. This is particularly illustrated in FIG. 15 insofar as there is shown to be a first gap (or allowance) 1586 between the top cap 1578 of the first backup linking structure 1572 and the bottom rim portion 1564 and also a second gap (or allowance) 1588 between the bottom cap 1580 of the second backup linking structure 1574 and the top rim portion 1562.

Given this arrangement shown in FIG. 15, when the improved mounting assembly 1508 (or the improved food

waste assembly of which the improved mounting assembly forms a part) is in the normal operational state as shown, the bottom enclosure piece 1512 and associated food waste disposer are fully supported relative to the top enclosure piece 1510 by the AV tension mount 1500. However, in some circumstances (e.g., after a long period of use) the AV tension mount 1500 may become elongated in terms of the distance between the bottom rim portion 1564 and top rim portion 1562 by comparison with what is shown in FIG. 15. 10 This can occur, for example, if the AV tension mount 1500 experiences creeping or becomes distended, or if it breaks or ruptures. If such elongation, break, or rupture occurs with respect to the AV tension mount 1500, the bottom enclosure piece 1512 (and associate food waste disposer) will still be 15 fully supported in relation to the top enclosure piece 1510 (and sink) by the first and second backup linking structures 1572 and 1574. When such support is provided by the 20 backup linking structures 1572 and 1574, the improved mounting assembly (and overall food waste disposer assembly) can be considered to be in an alternative backup support state.

Notwithstanding the illustration provided in FIG. 15, it should be appreciated that modified versions of the improved mounting assembly 1508 are also encompassed herein. In particular, it should be appreciated that, in some embodiments, the respective top cap(s) 1578 of one or more of the backup linking structures 1560 can be affixed to the bottom rim portion 1564 such that, when the improved mounting assembly is in the normal operational state, the respective bottom cap(s) 1580 of those respective backup linking structures 1560 are positioned beneath the top rim portion 1562. That is, in such embodiments, when the improved mounting assembly 1508 is in the normal operational state, the gap(s) (e.g., corresponding to the second gap 30 1588) occurring along the length(s) of those backup linking structure(s) 1560 occur between the top rim portion 1562 and the respective bottom cap(s) 1580 of those respective backup linking structure(s) (which can be said to "float" 35 below, or remain loose with respect to, the top rim portion). 40 Also, or alternatively, in some embodiments, the respective bottom cap(s) 1580 of one or more of the backup linking structures 1560 are affixed to the top rim portion 1562 such that, when the improved mounting assembly is in the normal operational state, the respective top cap(s) 1578 of those 45 respective backup linking structure 1560 are positioned above the bottom rim portion 1564. That is, in such embodiments, when the improved mounting assembly 1508 is in the normal operational state, the gap(s) (e.g., corresponding to the first gap 1586) occurring along the length(s) of those 50 backup linking structure(s) 1560 occur between the bottom rim portion 1564 and the respective top cap(s) 1578 of those respective backup linking structure(s).

Further, although not shown, in at least some other versions of the improved mounting assembly 1508 (although not shown), additional structures such as elastomeric grommets or bushings, or spring washers, can be added to one or more of the backup linking structures 1560 so as to occupy one or more of the first gap(s) 1586 or one or more of the second gap(s) 1588. That is, in some such embodiments, one or more of such additional structures can be positioned between one or more of the top cap(s) 1578 and the bottom rim portion 1564, and/or one or more of such additional structures can be positioned between one or more of the bottom cap(s) 1580 and the top rim portion 1564. By 60 positioning such additional structures along the respective rod portions 1576 in the locations of one or more of the first gap(s) 1586 and/or one or more of the second gap(s) 1588,

the manner in which the backup linking structure(s) 1560 serve to provide additional support when the AV tension mount 1500 elongates or breaks/ruptures can be less sudden or abrupt, because those additional structures allow for the weight of the bottom enclosure piece 1512 and associated food waste disposer to be transferred from the AV tension mount to the backup linking structures 1560 in a more gradual or softened manner. Also, such additional structures may lessen the noise of movement or jostling (e.g., side-to-side movement) of the backup linking structures 1560 relative to the bottom rim portion 1564 and/or the top rim portion 1562.

Additionally, in the improved mounting assembly 1608 of FIG. 16, the backup linking structures 1660 particularly include a first backup linking structure 1672 and a second backup linking structure 1674. In this embodiment, each of the first and second backup linking structures 1672 and 1674 includes a respective spring 1676 extending between the bottom rim portion 1664 of the top enclosure piece 1610 and the top rim portion 1662 of the bottom enclosure piece 1612 (at different circumferential locations around those respective rim portions). FIG. 16 particularly shows the improved mounting assembly 1608 when in a normal operational state such that the bottom enclosure piece 1612 (and associated food waste disposer) is fully supported relative to the top enclosure piece 1610 (and sink) by the AV tension mount 1600. That is, when the improved mounting assembly 1608 is in the normal operational state, the respective springs 1676 do not contribute to (or do not substantially contribute to) supporting the bottom enclosure piece 1612 (and associated food waste disposer) relative to the top enclosure piece 1610.

However, in some circumstances (e.g., after a long period of use) the AV tension mount 1600 may become elongated in terms of the distance between the bottom rim portion 1664 and top rim portion 1662 by comparison with what is shown in FIG. 16. This can occur, for example, if the AV tension mount 1600 experiences creeping or becomes distended, or may even break or rupture. If such elongation, break, or rupture occurs with respect to the AV tension mount 1600, the bottom enclosure piece 1612 (and associated food waste disposer) will still be fully supported in relation to the top enclosure piece 1610 (and sink) by the respective springs 1676 serving as the first and second backup linking structure 1672 and 1674. When such support is provided by the backup linking structures 1672 and 1674, the improved mounting assembly 1608 (and overall food waste disposer assembly) can be considered to be in an alternative backup support state. At the same time, in this embodiment, it should also be recognized that the respective springs 1676 need not only provide support to the bottom enclosure piece 1612 (and associated food waste disposer) when the AV tension mount 1600 reaches a particular elongated length or breaks/ruptures, but also can gradually begin to provide increasing support as the AV tension mount 1600 progressively increases in length from its length in the normal operational mode illustrated by FIG. 16.

Notwithstanding the illustration provided in FIG. 16, it should be appreciated that modified versions of the improved mounting assembly 1608 are also encompassed herein. For example, the particular types of springs that can serve as the first and second backup linking structures 1672 and 1674 can vary depending upon the embodiment. Also for example, additionally with reference to FIG. 17, the present disclosure further encompasses an improved mount-

ing assembly 1708 that includes components from each of the improved mounting assemblies 1508 and 1608 of FIG. 15 and FIG. 16.

More particularly, FIG. 17 shows a cutaway portion 1700 of the improved mounting assembly 1708, where the cutaway portion is illustrative of a section of the improved mounting assembly corresponding to a section 1702 shown in FIG. 15. It will be appreciated that, in this example embodiment, the improved mounting assembly 1708 again includes the bottom rim portion 1564 (of the top enclosure piece 1510) and the top rim portion 1562 (of the bottom enclosure piece 1512) of the improved mounting assembly 1508 of FIG. 15. Also, the improved mounting assembly 1708 includes backup linking structures 1760 (one of which is shown). Each of the backup linking structures 1760 has a respective rod portion 1776 extending between a respective top cap 1778 positioned above the bottom rim portion 1564 and a respective bottom cap 1780 positioned below the top rim portion 1562. Again, in this embodiment, each of the rod portions 1776 has a length that extends beyond the distance between the bottom rim portion 1564 and top rim portion 1562, when the improved mounting assembly 1708 is in the normal operational state as shown in FIG. 17. Accordingly, when the improved mounting assembly 1708 is in the normal operational state, at least one gap exists between the respective top cap 1778 and the bottom rim portion 1564 and/or between the respective bottom cap 1780 and the top rim portion 1562. In this regard, FIG. 17 particularly shows a gap (or allowance) 1788 between the bottom cap 1780 and the top rim portion 1562, although a gap could also be present between the top cap 1778 and bottom rim portion 1564.

Further, in the improved mounting assembly 1708 of FIG. 17 (and in contrast to the improved mounting assembly 1508 of FIG. 15), each of the backup linking structure 1760 also includes a respective spring 1786 that can each take the form of any of the springs 1676 of FIG. 16. Each respective spring 1786 in this embodiment can not only couple the bottom rim portion 1564 with the top rim portion 1562, but also can be positioned so as to extend around a corresponding one of the rod portions 1776, such that the respective rod portions 1776 respectively serve as guides for the respective springs 1786. In such an embodiment, it should be appreciated that, in the event that the improved mounting assembly 1708 switches from being in the normal operational state (as shown in FIG. 17) to an alternative backup support state due to elongation or breaking/rupturing of the AV tension mount (e.g., the AV tension mount 1500), backup support can be provided both by the respective springs 1786 and also by the respective rod portions 1776, top caps 1778, and bottom caps 1780.

Further, the present disclosure also is intended to encompass additional improved mounting assemblies that can include various combinations of components or features from two or more of the improved mounting assemblies or other embodiments described herein. For example, in some additional embodiments, the improved mounting assemblies 1508, 1608, or 1708 can additionally be implemented in combination with a trim shell assembly that extends around (for example) the food waste disposer and bottom enclosure piece. In some such embodiments, such a trim shell assembly can include a top wall that is positioned above the bottom rim portion 1564 or 1664 and is configured in a manner consistent with that described above in regard to FIG. 13 and FIG. 14, such that the trim shell assembly can also contribute to providing backup support as described above (e.g., in the same or substantially the same manner that the top wall 1324 and bottom rim 1406 can provide

backup support). Implementation of such a trim shell assembly additionally in relation to improved mounting assemblies such as the improved mounting assemblies **1508**, **1608**, or **1708** can also be helpful from the standpoint of providing a protective and/or aesthetically-pleasing enclosure around the backup linking structures **1560**, **1660**, or **1760**.

In view of above description, it should be appreciated that one or more of the embodiments of improved mounting assemblies or food waste disposer assemblies disclosed or encompassed herein can be advantageous in one or more respects. For example, in at least some embodiments encompassed herein, backup linkages linking an AV tube and enclosure (or linking top and bottom enclosure pieces), and/or other backup supports, can support the weight of a food waste disposer or other unit or structure attached (at least indirectly) to the enclosure, without having to entirely rely on the performance or creep resistance of any anti-vibration structure(s) (e.g., an annular elastomeric formation or other structure formed from TPE or other elastomeric material) that are normally employed (in tension) to couple the AV tube and enclosure. Further, in at least some embodiments encompassed herein, the backup linkages are integrally formed or molded in relation to one or both of the AV tube and enclosure, so as to form a one-piece substrate. The primary linkage(s) between the AV tube and enclosure, which are intended to be formed from TPE or another elastomeric material (or other material suitable for providing an anti-vibration link), can be formed by a separate molding, casting, injection, or overmolding step.

Formation of the backup linkages in this manner can facilitate manufacture of the improved mounting assembly, through the reduction of parts count or processing steps. Among other things, these manners of forming improved mounting assemblies can reduce or minimize the number of enclosure molds required for the project (e.g., by avoiding part-specific back-up tooling), can serve to enhance or maximize the flexibility to meet manufacturing/production shifts in a “mix” of products (since any mold can produce enclosures of a variety of types), and can generally serve to maximize an opportunity for there being commonality (in terms of a common manufacturing platform or process setup) at an as-molded stage.

Also, in at least some embodiments encompassed herein, the anti-vibration structure(s) employed to couple the AV tube and enclosure can be implemented by way of an overmolding process, such as through the overmolding of TPE or another elastomeric material (or other material suitable for providing an anti-vibration link), where the anti-vibration structure(s) are overmolded around one or more of the backup linkages. Such overmolded embodiments can be advantageous in one or more respects, including that the primary, anti-vibration linkage and the backup linkage structure(s) form an integrated package that is simple, elegant, and can avoid the interposition of debris between the different linkage structures.

Also, in at least some embodiments, such as where the backup linkages are springs, the backup linkages can be formed in a manner that introduces pre-loading, which can in some circumstances or embodiments introduced added or reduced levels of tension or compression to the overall overmolded structure after overmolding has occurred. Such added or reduced levels of tension or compression are configurable based upon the pre-loading, and can be introduced in a variety of manners that are intended to foster desired behavior, or enhance the longevity of operation, of the improved mounting assembly or portions thereof (e.g., to reduce the progression of creeping of the primary, anti-

vibration linkage structure(s)), or to permit additional support for unit(s)/structure(s) (e.g., food waste disposers) that will be supported by the mounting assembly.

Indeed, in at least some such embodiments, the substrate springs can allow some degree of pre-loaded tension or compression to be applied at the time of the overmolding process, if desired. Such pre-loading will result in an interim post-overmolding state to which the TPE or other such damping material is subjected when the preload is relaxed, and another state once the system is permanently loaded by the unit weight upon installation and during its service life. If a desired state of in-service overmold tension or compression can be identified (e.g., based on analysis and/or the testing of different iterations), then—taking the unit’s weight into account—the corresponding preload to attain that state can be calculated and designed into the overmold tooling/process. Further, even if processing or other limitations may make it difficult, in practice, to achieve or closely hold a particular desired state, it may be possible to use a degree of preloading during overmolding to at least hedge against an undesirable in-service state.

Also, at least some embodiments encompassed by the present disclosure can be advantageous in terms of the configurability of the mounting assemblies that is permitted, and/or the relevant simplicity with which the mounting assemblies can be manufactured, and/or the extent to which the same or substantially similar manufacturing machinery, tooling, or processing can be employed to manufacture/assemble a variety of different types or configurations of mounting assemblies. For example, in at least some embodiments in which the AV tube (or neck section of the substrate) can attach to the enclosure (or container body portion of the substrate) via a set of integral springs, such embodiments can be advantageous in that there are easy-to-implement manners of producing opposing pairs of springs (each pair by a different mechanism, due to the action of the tooling)—further for example, up to four essentially-similar springs in total. The cross-section of the springs can be configured to allow overmolding material (e.g., TPE) to flow into and fill the AV tube (or neck area of the part), during overmolding.

Some such arrangements are further advantageous in that the mounting assemblies can be manufactured/assembled using one or more manufacturing machines or techniques that are common both to such mounting assemblies employing anti-vibration linkage(s) and possibly other types of mounting assemblies. For example, a manner of manufacturing an improved mounting assembly with anti-vibration linkage(s) in combination with springs allows for a common gating system to be employed during manufacture, where the common gating system can be employed both for manufacturing the improved mounting assemblies with the anti-vibration linkage(s) (AV-mount mounting assemblies) and also for manufacturing other mounting assemblies that do not include such anti-vibration linkage(s) and can be considered rigid mounting assemblies.

Also, in at least some embodiments, the width or other geometrical attributes of the springs can be iterated (e.g., in prototype production and testing) in order to adjust the overall stiffness or system performance). Additionally, such an arrangement can be advantageous in that it is adaptable, and particularly is consistent with the addition of other substrate features in this area (e.g., between the AV tube and enclosure) as can be appropriate in certain embodiments or circumstances. For example, in a circumstance where a reduced number of springs, or springs of significantly reduced width or cross-section, would be appropriate to achieve desired system stiffness/AV performance—or if a

fill analysis determined additional flow was needed—then temporary bridges could be molded in place to augment the flow and then subsequently removed. The overmold would then be applied around, outside, and/or between the springs to seal off the remaining gap area. The molder's production transition from the AV-mount (substrate) version to the rigid version (non-overmolded) would require only an insert or slide change. The overmolding step can be varied according to the requirements of the design.

It is specifically intended that the present invention not be limited to the embodiments and illustrations contained herein, but include modified forms of those embodiments including portions of the embodiments and combinations of elements of different embodiments as come within the scope of the following claims.

We claim:

1. A mounting system for mounting a waste disposer, the mounting system comprising:

a tubular structure extending between first and second ends;

an enclosure structure that is configured to be able to support, at least indirectly, the waste disposer;

an elastomeric member coupled to each of the tubular structure, the enclosure structure, and the waste disposer; and

one or more backup support features that is or are configured to enable the enclosure structure and the waste disposer to be supported relative to the tubular structure when the elastomeric member is unable unilaterally to provide a desired support level of the enclosure structure and the waste disposer relative to the tubular structure.

2. The mounting system of claim 1, wherein the desired support level of the enclosure and the waste disposer is a tension force that is sufficient to prevent one or both of the enclosure structure and waste disposer from experiencing a positional change relative to the tubular structure that is equal to or greater than a first distance.

3. The mounting system of claim 2, wherein the first distance is a gap distance that separates a first one of the backup support features that is a first structural portion of the enclosure structure from a second one of the backup support features that is a second structural portion of the tubular structure when the mounting system is in a normal operational state in which the elastomeric member is able unilaterally to provide the desired support level.

4. The mounting system of claim 3,

wherein the enclosure structure includes at least an upper portion of a trim shell assembly that is positioned so as to extend at least partly around the waste disposer,

wherein the first structural portion of the enclosure structure constituting the first one of the backup support features includes a top wall having an inner rim defining an orifice through which the tubular structure extends so as to be coupled to the elastomeric member and, indirectly, so as to be coupled to an upper housing section of the waste disposer, and

wherein the second structural portion of the tubular structure constituting the second one of the backup support features includes a bottom rim of the tubular structure.

5. The mounting system of claim 1, wherein the enclosure structure is a trim shell assembly and the waste disposer is positioned substantially or entirely within, and supported by, the trim shell assembly.

6. The mounting system of claim 1, wherein the enclosure structure includes at least a first portion of a trim shell assembly that is positioned so as to extend at least partly around the waste disposer.

7. The mounting system of claim 1, wherein the one or more backup support features include:

a first rim portion of the tubular structure at or proximate the second end, the first rim portion having a first radius; and

a first wall of the enclosure structure, the first wall having an inner rim defining an orifice having a second radius that is less than the first radius,

wherein the first wall is positioned so that the tubular structure extends through the inner orifice, so that the first wall is between the first end and the first rim portion of the tubular structure.

8. The mounting system of claim 7 wherein, when the mounting system is in a normal operational state, the elastomeric member is able unilaterally to provide the desired support level of the enclosure structure and waste disposer relative to the tubular structure, so that a gap exists between the first rim portion and the first wall.

9. The mounting system of claim 8, wherein the one or more backup support features is or are configured so that, when the mounting system is in an alternative backup support state in which the elastomeric member is unable unilaterally to provide the desired support level, the first wall is in contact with and rests upon the first rim portion so that the enclosure structure and waste disposer are supported in relation to the tubular structure, with the enclosure structure being directly supported upon the tubular structure and the waste disposer being supported within the enclosure structure.

10. The mounting system of claim 7, wherein the elastomeric member includes an upper rim portion that is coupled to the second end of the tubular structure and a lower rim portion that is coupled to an annular wall of the enclosure structure that extends downward from the first wall to the lower rim portion so that, when the elastomeric member is able unilaterally to provide the desired support level, the enclosure structure is supported upon the first rim portion by the annular wall.

11. The mounting system of claim 10, wherein the lower rim portion of the elastomeric member is additionally coupled to an upper housing portion of the food waste disposer.

12. The mounting system of claim 1, wherein the one or more backup support structures include a plurality of backup linkage members, wherein each of the backup linkage members is coupled at least indirectly to each of the tubular structure and one or both of the enclosure structure and the waste disposer.

13. A food waste disposer assembly comprising the waste disposer and the mounting system of claim 1,

wherein the waste disposer is a food waste disposer having a food conveying section, a motor section, and a grinding section positioned between the food conveying section and the motor section, and

wherein the food waste disposer assembly includes a trim shell assembly within which is substantially positioned

the food waste disposer, wherein the enclosure structure either is or is included by the trim shell assembly.

14. The food waste disposer assembly of claim 13, wherein both of the enclosure structure and the food waste disposer are directly connected to and supported by a bottom rim portion of the elastomeric member.

41

15. The mounting system of claim 14, wherein the elastomeric member is an annular elastomeric member, is made of a thermoplastic elastomer (TPE) material, and serves to prevent or reduce a communication of vibration from one or both of the food waste disposer and the enclosure structure to the tubular structure. 5

16. A waste disposer assembly comprising:

a waste disposer;

a mounting assembly including

a first structure having a first end and a second end, and 10 configured to be coupled at or proximate the first end to a support structure;

a second structure having an additional end, wherein 15 the waste disposer is at least indirectly attached to and supported by the second structure;

an anti-vibration linking structure coupled to each of 20 the second end of the first structure, the additional end of the second structure, and the waste disposer; and

25 at least one backup support feature that is configured to support, at least in part, the second structure and the waste disposer relative to the first structure, in an operational circumstance in which the anti-vibration linking structure is unable to provide a desired support level of the second structure and the waste disposer relative to the first structure.

17. The waste disposer assembly of claim 16, wherein the second structure is a trim shell assembly, and wherein the at least one backup support feature includes:

a first rim portion of the first structure at or proximate the second end, the first rim portion having a first radius; 30 and

an upper wall of the enclosure structure, the upper wall 35 having an inner rim defining an orifice having a second radius that is less than the first radius,

wherein the upper wall is positioned so that the first structure extends through the inner orifice, so that the upper wall is between the first end and the first rim portion of the first structure.

18. The waste disposer assembly of claim 17, 40 wherein the at least one anti-vibration linking structure is an annular elastomeric member,

wherein, when the waste disposer assembly is in a normal operational state, the annular elastomeric member is able unilaterally to provide the desired support level of the trim shell assembly and the waste disposer relative to the first structure, so that a gap exists between the first rim portion and the upper wall, and

wherein, when the waste disposer assembly is in an alternative backup support state that is the operational 45

42

circumstance in which the anti-vibration linking structure is unable to provide the desired support level, the upper wall is in contact with and rests upon the first rim portion so that the gap no longer exists between the first rim portion and the upper wall, and so that the second structure and waste disposer are supported in relation to the first structure, with the waste disposer being supported within the second structure.

19. A method of operating a waste disposer assembly comprising:

providing a waste disposer and a mounting assembly, wherein the mounting assembly includes

a first structure having a first end and a second end and 10 configured to be coupled at or proximate the first end to a support structure;

a second structure having an additional end, wherein 15 the waste disposer is at least indirectly attached to and supported by the second structure;

an anti-vibration linking structure coupled to each of 20 the second end and the additional end, and

at least one backup support feature;

first supporting the second structure and the waste disposer relative to the first structure by the anti-vibration linking structure when the waste disposer assembly is in a normal operational state;

second supporting the second structure and the waste disposer relative to the first structure, at least in part, by the at least one backup support feature, when the waste disposer assembly is in an alternative backup support state in which the anti-vibration linking structure is unable to provide a desired support level of the second structure and the waste disposer relative to the first structure,

wherein the at least one backup support feature includes a first portion of the second structure at or proximate the additional end and a rim portion of the first structure at or proximate the second end, and wherein the second supporting includes supporting the first portion of the second structure upon the rim portion of the first structure.

20. The method of claim 19 wherein, when the waste disposer assembly is operating in the normal operational state, a gap exists between the first portion of the second structure and the rim portion of the first structure and, when the waste disposer assembly is operating in the alternative backup support state, the gap between the first portion of the second structure and the rim portion of the first structure no longer exists due to contacting of the first portion and rim portion.
